INTERLOCKING SYSTEM FOR RAILROADS

Sedgwick N. Wight, Rochester, N. Y., assignor to
General Railway Signal Company, Rochester,
N. Y.

Application April 21, 1934, Serial No. 721,696

45 Claims. (Cl. 246—134)

This invention relates to interlocking systems for railroads, and more particularly pertains to such a system in which a miniature track layout in a control office has located thereon the controlling buttons or levers for setting up the desired routes, and in which all of the interlocking between the various traffic controlling devices is accomplished by the proper selection of electric circuits.

10 The present invention contemplates that a miniature track layout is located in the central control office which corresponds to the actual track layout in the field. On this miniature track layout are located route buttons or levers at those 15 points on the miniature track layout which correspond to the signal locations on the actual track layout. In order to establish the movement of traffic in a particular direction over a particular track-way route, the operator actuates the 20 buttons or levers in the desired route in a direction corresponding to the desired traffic direction.

Instead of providing individual switch and signal control levers which are not on the miniature track diagram, as is the usual practice, the actuation of the route buttons at the two opposite ends of a desired route serve to both control the track switches in the field to the required positions for that route and to cause the proper signal to clear to allow the passage of traffic providing it is safe to do so.

Such an organization, as contemplated in accordance with the present invention, has the advantages over the usual practice in that the operator is not required to direct his attention away from the miniature track diagram in order to accomplish switch controls, but may maintain his attention along the desired route and actuate such route determining buttons or levers as are located in that route.

40 Also, the arrangement contemplated in accordance with the present invention has a distinct advantage over previous route lever systems in that formerly a separate lever was required for each of the possible routes so that a large number of levers would be required in connection with each signal location. The present invention preferably provides but a single button at each signal location and a route is determined by the actuation of the buttons at the two opposite ends of such route.

45 The means employed in the embodiment of the present invention to accomplish the setting up of the routes following the actuation of the route buttons is provided in the form of electric circuits

selected by suitable contacts on the route buttons, so that following the actuation of the buttons at the opposite ends of a route, a relay which corresponds to that particular route is energized with a polarity in accordance with the direction 5 of traffic to be established over such route. This route relay, thus selected, is employed to set up individual controls for the track switches involved in that route and for the signal governing traffic over such route. These individual controls 10 are transmitted to the track switches and signals in the actual track layout, which are interlocked by circuits that are preferably located adjacent to the track layout so as to provide the greatest 15 degree of safety.

Thus, one object of the present invention may be said to reside in an arrangement of control wherein the operator is associated with the actual trackway conditions in terms of complete routes and directions of traffic movement which are the 20 desired ultimate results, instead of in terms of the differentiated functions of such results.

Other objects, purposes, and characteristic features of the present invention will be in part obvious from the accompanying drawings and in 25 part pointed out, as the description of the invention progresses.

In describing the invention in detail, reference will be made to the accompanying drawings, in which like reference characters designate the 30 same parts throughout the several views; in which like letters in the reference characters designate similar functions or relationships with the distinctiveness between such reference characters 35 provided by the use of distinctive preceding numerals; in which like preceding numerals in the reference characters, when applied to different letters, represent the inclusion of such devices within a particular group; and in which:— 40

Figs. 1 and 2 when placed end to end constitute an interlocking system illustrated diagrammatically and constructed in accordance with the present invention as applied to a simple track layout including two crossovers and a turn-out 45 track;

Fig. 3 illustrates the route selecting circuits which are employed at the field location for the track layout illustrated and which connect to the signal control wires of Fig. 1 in place of the 50 Fig. 2 where such control is merely indicated;

Fig. 4 illustrates the detail switch control means for a single switch, it being understood that similar apparatus would be employed for each switch in the track layout, and it being understood that 55

this Fig. 4 shows the detail of the switch control merely indicated conventionally in Fig. 2;

Fig. 5 illustrates the individual signal control and selection for certain of the signals, it being understood that similar controls would be provided for each of the remaining signals in the track layout and it being understood that this Fig. 5 taken with Fig. 4 shows the detail of the signal control merely indicated in Fig. 2; and

10 Fig. 6 illustrates a modified form of switch control to accomplish certain additional features in accordance with the present invention.

Fig. 7 is a first modification of Fig. 1.

15 Figs. 8, 9 and 10 illustrate a second modification of Fig. 1.

Instead of showing a complete circuit arrangement by placing a large number of sheets side by side, a simplified method of disclosure has been employed wherein all of the control circuits for 20 any one relay are shown in a continuous relationship; while all of the circuits which that relay may control are distributed between the several sheets of drawings upon which that relay is shown in block form.

25 For the purpose of further simplifying the illustration and facilitating in the explanation thereof, the conventional parts and circuits constituting the embodiment of the invention have been shown diagrammatically and certain conventional illustrations have been employed, the drawings having been made more with the idea of making clear the purpose and principles of the present invention together with its mode of operation than with the idea of illustrating the specific construction and arrangement of parts that would probably be employed in practice.

The various relays and their contacts are illustrated in a conventional manner and symbols are employed to indicate connections to the terminals 40 of batteries or other suitable sources of electric current supply instead of showing all of the wiring connections to such terminals.

The symbols (+) and (-) are employed to indicate the positive and negative terminals respectively of suitable batteries, or other sources of electric energy; and those terminals with which these symbols are used are presumed to have current flowing from the positive terminal designated (+) to the negative terminal designated (-). The symbols (B+) and (B-) indicate connections to the opposite terminals of suitable batteries, or other sources of energy which have central or intermediate taps designated (CN), and the circuits with which these symbols are used, may have current flowing in one direction or the other depending upon the particular terminal used in combination with the intermediate tap designated (CN). For convenience in the illustration, certain of those 55 terminals which are designated (CN) are considered to be connected together in place of showing a common wire connection as would be necessary in practice. The symbols employed with any one circuit presumably designate the terminals of the same battery or other suitable source, but as many separate sources may be provided as found necessary, or as many sources may be combined in a single source as found necessary in the practice of the invention. If 60 alternating current is employed, then these symbols should be considered to represent the instantaneous relative polarities of the respective terminals.

Where groups of devices are referred to in a 75 general way, such devices will be designated by

the letters or preceding numerals characteristic of such group instead of citing each specific reference character of the group.

Apparatus

5

In the accompanying drawings, the invention has been shown applied to a simple track layout including a stretch of double track having two crossovers and one turn-out track (see Fig. 2); but it should be understood that the invention is not limited, as thus shown, to the control of the switches and signals of such a simple track layout, but may be extended for any desired number of switches and signals and may be readily applied to all types of track layouts commonly 15 found in interlocking plants.

The stretch of double track includes main line rails 200 and main line rails 201, while the turn-out track includes rails 202 (see Fig. 2). The main line 200 is connected to the main line 201 20 through switches 2TS and 3TS forming opposite ends of one crossover, and track switches 4TS and 5TS forming the opposite ends of a second crossover. The turn-out track 202 is connected to the main track 201 by the track switch 7TS. 25

The track switches 2TS, 3TS, 4 TS, 5TS and 7TS are respectively operated by power switch machines 2SM, 3SM, 4SM, 5SM and 7SM, which switch machines may be of any suitable type, such for example, as disclosed in the patent to 30 W. K. Howe, Patent No. 1,466,903 dated September 4, 1923.

A signal 10A is provided to control east-bound traffic over the main track 200; while a signal 30A is provided to govern west-bound traffic over 35 the main track 200. A lower arm signal 10B is provided to control east-bound traffic from the main track 200 over the crossover having switches 4TS and 5TS onto the main track 201; while a lower arm signal 30B is provided to control west-bound traffic from the main track 200 over the 40 crossover having switches 2TS and 3TS onto the main track 201.

A signal 20A is provided to govern east-bound traffic over the main track 201 up to a signal 45 40EA, which then governs east-bound traffic over the main track 201. Both the signal 20 and the signal 40E are provided with lower arm diverging route signals 20B and 40EB respectively. The signal 40E is also provided with a call-on signal 50 40EC which governs traffic either over the main track or the turn-out track independently of track occupancy conditions as hereinafter more specifically pointed out.

The signals 50 and 40WA govern the west-bound traffic over the main track 201, while the lower arm signal 40WB governs the diverging route from the main track 201 onto the main track 200 over the crossover having switches 4TS and 5TS. 60

The section of track between the signal 10 and the signal 30 forms a track circuit section and is provided with a track relay 24T and a suitable track battery (not shown). Similarly, the main track 201 forms a track circuit section between 65 the signal 20 and the signal 40 and is provided with a track relay 35T and the usual track battery (not shown).

A section of the main track 201 forms a track circuit section between the signal 40 and the 70 signals 50 and 60, and is provided with a track relay 7T and the usual track battery (not shown).

The main track 200 is probably provided with a track circuit section east of the signal 30 and the usual automatic signalling although this is 75

a matter determined by the conditions of a particular situation in practice, and therefore has not been shown. The main track 201 and the turn-out track 202 have extending track circuit sections which are respectively provided with track relays 8T and 9T, and the usual track batteries (not shown).

These track circuits could, of course, be subdivided or lengthened as desired, and arranged in accordance with any of the usual practices.

The track switches of a crossover are controlled together, as indicated by the dotted lines in Fig. 2. Therefore, a single lock relay 23L is associated with the track switches 2TS and 3TS; a single lock relay 45L is associated with the track switches 4TS and 5TS; and, a single lock relay 7L is associated with the track switch 7TS. Each of these lock relays L is a neutral relay with slow release and quick pick-up characteristics.

The controls directed to the traffic controlling devices illustrated in Fig. 2 have been shown as dotted lines which merely indicate the ultimate destination of the controls originating in Fig. 1, it being understood that the details and interrelation of such controls indicated by these dotted lines are shown in detail in other figures of the drawings, as more specifically pointed out hereinafter.

With reference to Fig. 1 of the accompanying drawings, the control office is illustrated as including a miniature track diagram having a track layout corresponding to the actual track layout in the field.

A movable miniature track switch point is preferably provided to represent each of the track switches of the track layout in the field, such as miniature switch points 2ts, 3ts, 4ts, 5ts, and 7ts. These miniature track switch points may indicate the actual positions of their corresponding switches in a manner disclosed in my pending application, Ser. No. 431,748, filed February 27, 1930. However, in a system as provided by the present invention, it is desirable to have these miniature switches controlled in accordance with the proposed route as set up by the operator in a manner disclosed herein.

Associated with each of the miniature track switch points, is a lock light which indicates whenever that track switch is locked against operation. Although such lock lights have not been illustrated in connection with the miniature track switch points in Fig. 1, such a lock light has been specifically illustrated for the track switch 7TS as indicator 71 in Fig. 4 of the accompanying drawings where its control is disclosed.

At each point on this miniature track lay-out corresponding to the point on the actual track lay-out where signals are located, is located a suitable rotary control lever or button designated by the letter reference characters RB and indicated as associated with the corresponding signals in the field by the preceding numerals which correspond with the numbers of such signals.

These rotary route buttons RB have been shown as having arrows thereon which indicate the existing position of the buttons which are normally in vertical positions, but any other suitable method of designation may be employed. When a route button is rotated to the right, it designates the setting up of traffic in the right hand direction; and, when a route button is rotated to the left it designates the setting up of traffic in a left hand direction. Each of these route buttons RB operate suitable contacts.

More specifically, the route button 10RB operates contacts 11 and 12; the route button 20RB operates contacts 21 and 22; the route button 30RB operates contacts 31 and 32; the route button 40RB operates contacts 41, 42, 43 and 44; the route button 50RB operates contact 51; and the route button 60RB operates contact 61. Each route button RB, when rotated in a particular direction, operates its contacts in the same direction to contact closing positions.

It is of course to be understood that although rotary route buttons have been illustrated and contemplated in accordance with the present embodiment of the invention, that other suitable manually operable contact means might be employed such as a three-position snap switch or the like.

Although no signal indicators have been shown on the track diagram, it is contemplated that a signal indicator is associated with each route button representing a signal location and is caused to be illuminated when its respective signals are cleared, so that the operator is continuously advised as to the trackway conditions.

When two route buttons RB are operated at the opposite ends of a route in the same direction, a route relay is picked up which corresponds to that particular route and thereby prevents all other route relays of conflicting routes from being energized by reason of its contacts which are included in the pick-up circuits for all such conflicting route relays. Each of these route relays is energized with a polarity in accordance with the direction of traffic to be set up, all of which will be explained more in detail herein-after, it being sufficient for the present to merely enumerate the route relays thus controlled and point out that these relays are preferably of the polar-neutral type in which the neutral contacts are picked up only while the relay is energized and in which the polar contacts remain in their last actuated positions.

A route relay 10-30 (see Fig. 1) controls the traffic between signals 10 and 30 (see Fig. 2) and is provided with contacts 15, 18, 52, 53, 54 and 55. A route relay 20-30 controls traffic between the signals 20 and 30 over the crossover including switches 2TS and 3TS, and is provided with contacts 13, 16, 26, 56, 57, 58 and 59. A route relay 10-40 controls traffic between the signals 10 and 40 over the crossover including switches 4TS and 5TS, and is provided with contacts 14, 19, 27, 46, 47, 48 and 49. A route relay 20-40 controls traffic between the signals 20 and 40, and is provided with contacts 17, 25, 33, 34, 36 and 37. A route relay 40-50 controls traffic between the signals 40 and 50, and is provided with contacts 29, 62, 63 and 64. A route relay 40-60 controls traffic between the signals 40 and 60, and is provided with contacts 28, 65, 66 and 67.

Signal controls are provided in accordance with the particular route relay or relays by the energization of suitable signal control buses, namely, buses 13, 14, 15, 16, 17, 18 and 19.

For the control of the track switches, suitable switch control relays Z are provided, one for each individual track switch and one for each crossover, which are more specifically illustrated as relays 7Z, 45Z and 23Z. These relays are controlled by the energization of suitable switch control buses 80, 81 and 82 which are energized with a particular polarity in accordance with the particular route relays which are energized following the establishing of a route on the miniature track diagram. The switch control relays Z

are preferably of the two-position magnetic stick type, so that their armatures remain in the positions to which they were last actuated in accordance with the last polarity applied to their individual control buses irrespective of subsequent deenergization of the buses. Various other devices are preferably associated with the switch control relays Z in the control office for transmitting the switch control to the field station over a line circuit, all of which will be pointed out more specifically hereinafter.

Associated with the signal 40E, there is suitable apparatus located in the control office to transmit a call-on signal control in order to govern the signal 40EC in the event that the trackway in advance of the signal is occupied, and it is desired to advance a train by the signal in spite of such occupancy. The apparatus in the control office required for this additional control includes a call-on button 40EPB and a call-on stick relay 40ECS. The call-on button 40EPB is preferably located somewhere on the operating panel so as to be associated with the route button 40RB, and is self restoring. It may be noted that such control might well be embodied in the route button 40RB by providing that if such button were depressed as a push button, it would control the call-on contact 40ECB, thereby embodying both the regular route control and the special call-on control in the route button. This could of course be applied to as many route buttons as have call-on signals associated therewith.

It is believed that the characteristic features and purposes of the present invention will be more clearly understood by now discussing the general operation of the system with more specific reference to Figs. 1 and 2, it being understood that, the detailed apparatus required to accomplish the control and interlock in Fig. 2, is illustrated more specifically in Figs. 3, 4 and 5, and will be described in detail following a description of the general operation.

General operation

45 *Normal conditions.*—Although the track switches TS are usually left in their last operated positions, they have been shown in positions required for the passage of main line traffic (see Fig. 2). The signals are of course normally "at-stop". As the signals are illustrated as being of the color light type, it is to be understood that the lower or red indicator of each signal is normally illuminated (see Fig. 5 for details).

With the track sections unoccupied, the track relays T are normally energized with their contacts picked up.

With all of the route buttons RB in their normal positions (vertical) indicated by the arrows on the buttons, the signals governing traffic over the track-way are at stop and all of the relays in Fig. 1 are de-energized.

60 *Establishing a route.*—In order to obtain an understanding of the operation of the system, we will assume that the operator desires to establish a route from the signal 20 to the signal 40E. To do this, the operator turns the route button 20RB to the right and then directs his attention along the track-way to ascertain whether the switches in that route are unlocked as indicated by the lock lights (mentioned above and explained in connection with Fig. 4), and then rotates the route button 40RB to the right. The contemporaneous positioning of the route buttons 20RB and 40RB in right hand positions closes contacts 22 and 42 respectively in right hand po-

sitions, thereby establishing an energizing circuit for the route relay 20-40 from the positive terminal of a suitable source indicated as (+), through a circuit including contact 22 in a right hand position, back contact 26 of route relay 5 20-30, back contact 27 of route relay 10-40, winding of route relay 20-40, contact 42 in a right hand position, to (-).

This energization of the route relay 20-40 opens its back contacts 17 and 25 which prevent 10 the establishment of conflicting routes, as will be considered later.

The picking up of contacts 36 and 37 of route relay 20-40 applies positive energy from (B+) to both of the switch control buses 81 and 82, 15 which causes the energization of the polar switch control relays 45Z and 23Z respectively and the actuation of their contacts to right hand positions. The track switches are controlled by these relays, as indicated by the dotted lines extending 20 from their contacts to their respective switch machines. This is possible because their respective lock relays 45L and 23L are still energized.

The application of energy to the route relay 20-40, as above pointed out, causes its polar contact 34 to assume a right hand position and its neutral contact 33 to be picked up which applies positive potential from (B+) to the signal control bus 77. Such energization of the signal control bus 77, through the apparatus described 30 in detail hereinafter, causes the de-energization of the lock relays 23L and 45L after an interval of time measured by their release periods (see Fig. 5) following which, with the track switches in proper positions, the signal 20A is cleared as 35 indicated by the dotted line 77 extending to such signal in Fig. 2.

The clearing of the signal 20A allows the passage of a train over the main track 201 up to the signal 40E which still indicates stop. In other words, the setting up of a route on the miniature track diagram by actuating the route buttons at each end of such route establishes the direction of traffic and permits the movement of traffic up to the signal location represented by the last route button positioned, which in this case was the route button 40RB corresponding to the signals 40.

It should be noted that the control of a route relay, such as route relay 20-40, establishes simultaneously the switch and signal controls. Thus, in order to insure that the switch machines SM receive their controls for a sufficient period to cause their operations to the desired positions, the lock relays L are made slow acting because such lock relays are de-energized immediately following the energization of the signal control buses. However, the signals cannot clear until all of the lock relays in the route have become de-energized and the track switches in such route are in proper positions (see Fig. 3). This may be stated in a little different manner by saying that although the switch and signal controls are established simultaneously, their effective response is caused to be sequential by the means of suitable time delay period inserted in the control circuits so as to provide for the control of the switches and signals sequentially.

We will now assume that the train is ready to accept a clear signal from signal 40E but a route has not yet been established beyond such signal. If the operator desires to allow the train to continue on the main track 201 in an east bound direction he operates the route button 50RB to the right, provided its lock light is not illuminat- 75

ed, which causes the route relay 40-50 to be energized by a circuit closed from (+), through a circuit including contact 43 in a right hand position, winding of route relay 40-50, back contact 28 of route relay 40-60, contact 51 in a right hand position to (-).

The energization of the route relay 40-50 closes front contact 64 which applies positive potential from (B+) to the switch control bus 80 10 thereby actuating the polar contacts of the switch control relay 7Z to right hand positions. This causes the track switch 7TS to assume a normal position for main line traffic, after receiving its control while the slow releasing lock 15 relay 7L is still energized.

The energization of the route relay 40-50, in the manner just described, causes the polar contact 63 to be actuated to a right hand position and the neutral contact 62 to be picked up which 20 energizes the signal control bus 73 from (B+) through these contacts of the route relay 40-50 and back contact 69 of the call-on stick relay 40ECS, which causes the clearing of the signal 25 40EA as soon as the route is properly established, which is indicated by the dotted line 73 of Fig. 2. The train may then accept such signal 40EA and proceed in accordance therewith up to the next signal governing east bound traffic. As there is no east bound signal at the location corresponding 30 to the west bound signal 50, then the train will proceed beyond the control illustrated in the present disclosure, which is indicated as automatic territory by reason of the track circuit control.

Following the passage of the train past the signal 20A, in the case above assumed, the operator may return the route button 20RB to its normal position, and the same is true of the route button 40RB. In other words, the route is established 40 by actuating the route buttons in advance of the train and the route is put to stop by the return of the route buttons to normal positions behind the train.

Let us now assume that the operator desires 45 to cause the setting up of a route from the signal 20 to the signal 30. With the route buttons 10RB, 20RB, 30RB and 40RB in their normal positions, the operator may establish such a route by turning the route buttons 20RB and 30RB to the right. This energizes the route relay 20-30 by a 50 circuit closed from (+), through a circuit including contact 21 in a right hand position, back contact 18 of route relay 10-30, windings of route relay 20-30, back contact 19 of route relay 10-40, back contact 25 of route relay 20-40, contact 32 of route button 30RB in a right hand position, to (-).

This energization of the route relay 20-30 energizes the switch control buses and the signal 60 control buses in a manner to establish a route over the cross-over including the track switches 2TS and 3TS by clearing the signal 20B for such route after the switches have responded.

The particular feature to be noticed in connection 65 with the establishment of such a route is the interlock between the route relays 10-30, 20-30, 10-40 and 20-40. In other words, these route relays are so interlocked that two parallel routes for either direction may be established simultaneously over the main tracks 70 200 and 201, but so arranged so that in the event of the establishment of a route over one of the main tracks, a conflicting route cannot then be established.

If we notice the arrangement of contacts for

the route just considered, namely, with the route buttons 20RB and 30RB operated to the right, the route relay 20-30 opens the circuit for the route relay 20-40 at back contact 26, thus preventing the conflict of controls that might be existent were it possible for the actuation of the route relay 20-40 following the energization of the route relay 20-30. For example, assuming that the operator has just operated the route buttons 20RB and 30RB, and then operates the route 10 buttons 40RB and 50RB, the route relay 20-40 might be energized were it not for the back contact 26 of the route relays 20-30.

Similarly, the route relay 20-30 opens back contact 16 preventing the energization of the route relay 10-40, and likewise opens back contact 13 preventing the energization of route relay 10-30.

In other words, the route relays 20-30 and 10-40, which are conflicting routes with regard 20 to the two main tracks, open the route circuits for each of the remaining routes, but the route relays 10-30 and 20-40 which are for parallel routes open only those route circuits for the route relays which govern conflicting routes. 25 Thus, the route relays which are governed by the route buttons are so interlocked as to prevent any conflict between the controls which are to be set up and transmitted to the individual traffic controlling devices in the field.

Although the arrangement and interlock between the route relays controlled by the route buttons RB is not organized to enforce or require a definite sequence in the operation of the route buttons in the establishment of a route, it is desirable 30 from an operating standpoint that the route buttons be operated in predetermined sequences so that the operator will clearly have in mind the direction of traffic established over a route. For example, in the establishment of a route from the signal 20 to the signal 40, it is desirable 35 to operate to the right the route buttons 20RB and 40RB sequentially in that order, so that not only does the direction of rotation of the route buttons determine the direction of traffic and bring to the operator's mind the direction of traffic which he is establishing, but also the motion of his arm from one point to the next definitely brings to mind the direction of traffic which is being set up.

The east and west bound signals 40 have been 40 shown in Fig. 1 as controlled by a single route button 40RB. This has been done so as to illustrate the manner in which two signals for opposite directions at a single location can be controlled by a single route button, and the manner in which the signal control relays GZ at such a location are interrelated as illustrated in Fig. 3. This arrangement is particularly desirable at 45 certain locations in a track layout where there may be conflicting routes requiring double locations of this character, but in those cases where double locations of this character are adjacent to a crossover so that in some cases the signals control routes which conflict with a possible 50 parallel route, it is desirable to employ two route buttons for such a location, as illustrated in Fig. 7 of the accompanying drawings.

With reference to Fig. 7, it will be seen that the portion of the miniature track diagram of Fig. 1 associated with the route buttons 30RB and 40RB has been repeated and is shown as including the same route button 30RB in the track reproduction corresponding to the main track 200 while the route button 40RB has been re- 55 70 75

placed by route buttons 40RBW and 40RBE. The route button 40RBW is indicated as controlling the contacts 41 and 42 of Fig. 1 which control the same circuits as in Fig. 1; and similarly, the route button 40RBE controls the contacts 43 and 44 which in turn control the same circuits as illustrated in Fig. 1.

This arrangement of Fig. 7 being assumed to be included in Fig. 1 in place of route button 10 40RB, provides the more desirable arrangement where parallel routes are possible as in the track layout shown in Fig. 2, as it relieves the operator from remembering any predetermined order in which certain of the route buttons are required to be operated in complicated movements. This may be best considered by way of an example.

Let us assume that a train is approaching ready to accept a clear indication from the signal 20 40EA, another train is standing ready to accept a clear indication from the signal 10A, and a third train is approaching the signal 20A, which train the operator is desirous of stopping at such signal 20A. Assuming that the signals 20A and 25 40EA are clear and the route buttons 20RB, 40RBW, 40RBE and 50RB are operated to the right, the operator returns the buttons 20RB and 40RBW to their stop positions in order to place the signal 20A at stop to stop the approaching 30 train. But the operator desires to allow the train which is approaching the signal 40EA to continue, so he does not disturb the route buttons 40RBE and 50RB. The operator now positions the buttons 10RB and 30RB to the right and to 35 allow the train standing ready to accept the signal 10A to proceed.

The separate control of contacts 41 and 42, and also the contacts 43 and 44 by the route buttons 40RBW and 40RBE respectively provides 40 independent control of the parallel routes at any time and in any sequence. If the example assumed above were applied to Fig. 1 without the modification of Fig. 7, it is apparent that the operation of the route button 40RB to a stop position would not be possible and still retain the signal 40EA clear. Thus, only the route button 20RB could be returned to its stop position to place the signal 20A at stop, and if after such operation of the route button 20RB, the route button 10RB were operated to the right, then 45 an undesired setting up of a route over the crossover would be effected because of the contemporaneous operation of the route buttons 10RB and 40RB to the right before the operation of the route button 30RB to the right. However Fig. 50 1 modified as in Fig. 7 obviates such an undesired possibility.

To summarize the above, it may be stated that Fig. 1 illustrates the control of a double signal 60 location by a single route button RB for traffic movements in connection with conflicting routes both over a single track switch and over a crossover connecting with possible parallel routes. Such control of a double signal location is entirely 65 possible, and clearly illustrates the association of the apparatus required, but in order to furnish greater facility in the case of parallel routes a double signal location is preferably provided with two route button controls as illustrated in Fig. 7. This method of illustration has thereby 70 simplified the present disclosure in that the control of two separate double locations has not been required in the drawings, that is, a double signal location associated with possible parallel routes 75 and another double signal location shown entirely

separate from parallel routes and only with diverging routes over single track switches.

In the practice of the invention, it is desirable that it be required that a route button be operated at each end of a route irrespective of the 5 intermediate route buttons which may be located between such opposite ends of a route for signals governing the opposite direction. In other words, when a route is established from one signal to the next succeeding signal for that direction, it is 10 preferable that the route buttons for such signals both be required to be operated before such route will be cleared to allow the passage of traffic, even though there may be some intermediate route buttons which will govern signals for the opposite 15 directions. For example, the route represented by the route buttons 20RB and 40RB of Fig. 1 is illustrative of what is meant, as the signal 20A can clear only when the route button for the next signal governing the same direction is properly 20 operated.

However, in some cases, such as in the case of signals 50 and 60, for example, the control of a train is taken away from the operator as the train passes onto automatic signalling territory, 25 and hence, it becomes unnecessary to have a route button representative of the end of the route of that train at the end of such automatic territory. Also, it may be that the routes in the interlocking plant governed by such route buttons connect with unsignalled territory and thus there would be no signal at the end of such route. Also, it may be that at the particular interlocking plant head-on protection only is desired rather than complete control of the train for switching purposes. Thus, the present disclosure does not illustrate all of the various operating conditions which may be encountered in practice but rather discloses particular apparatus and mode of operation of such apparatus which is applicable to all 30 types of track lay-outs.

In view of the above, it is therefore proposed in accordance with the invention to indicate by different color, or by some other suitable means, whether a particular route button is representative of signals governing traffic in both directions or a signal governing traffic in a single direction, 45 so that the operator will be adequately advised as to the possible control which he has over train movements.

It should also be understood that route buttons RB may be located at points where there are no signals for the purposes of providing optional routes. For example, a route might be set up from the signal 20 to the signal 40 by way of the 50 track switches 3TS, 2TS, 4TS and 5TS all in reverse positions. However, in accordance with the present disclosure, such an optional route is capable of being set up by use of the emergency manual levers illustrated in connection with the 60 switch control relays Z and discussed in the consideration of Fig. 6 of the accompanying drawings.

Call-on signal control.—From the above description it will be apparent that a particular signal is cleared by energizing its signal control bus with positive potential from (B+) by the route relay governing the particular route set up at that time. There are times when the automatic signals will not clear due to the occupied condition 65 by a train of the section of track which they govern, but it still is desirable to be able to at times send a switching engine or the like on to such section in order to facilitate the proper and desired train movements. The signal which can 70

clear under such circumstances is termed a "call-on signal."

In accordance with the present invention, means has been provided in the central office for clearing such a call-on signal in connection with signal 40E, when the signal indication means (not shown) advises the operator that the signal 40EA or 40EB has not cleared due to the occupied condition of the track-way in advance. This can be accomplished by the operator only while the route is still set up by the route buttons RB, if he actuates the call-on signal button 40EPB. This closes a pick-up circuit for the call-on stick relay 40ECS, providing governing route relay is energized, by a circuit closed with either the route relay 40-50 or the route relay 40-60 energized for east bound traffic. For example, assuming a route to be set up with the route buttons 40RB and 50RB operated to the right and the route relay 40-50 energized, a pick-up circuit for the 40ECS is closed from (B+), through a circuit including front contact 62 of relay 40-50, polar contact 63 of relay 40-50 in a right hand position, windings of relay 40ECS, back contact of push button 40EPB, to (CN). On the other hand, if route buttons 40RB and 60RB are operated to the right and the route relay 40-60 is energized instead of the route relay 40-50, an energizing circuit is closed from (B+), through a circuit including front contact 65 of route relay 40-60, polar contact 66 of route relay 40-60 in a right hand position, windings of relay 40ECS, back contact of push button 40EPB, to (CN).

35 The relay 40ECS remains energized following its initial energization, by reason of its stick contact 68 applying (CN) to its right hand terminal in place of the self-restoring push button 40EPB so long as the governing route relay is still energized.

The energization of the relay 40ECS applies negative potential from (B-) to the signal control bus 73 and causes the signal 40EC to clear, in a manner described in detail in connection with Fig. 5, but indicated in Fig. 2 by the dotted line 73.

From this it is seen that the route must be initially established by the route buttons RB and if the signal for such route does not then clear due to the presence of traffic in advance and it is desirable to cause a train to proceed upon instructions to stop upon sight of an obstruction, then the operator may actuate the call-on button PB associated with that route to cause the call-on signal associated with such route to be cleared. It is to be understood in this connection that although only the signal 40E has been provided with a call-on signal, that as many call-on signals may be provided as found necessary in the practice of the invention.

Detailed operation

Switch control.—In connection with the general operation, it was pointed out how the actuation of a route relay for a particular route applied positive or negative potential to the switch control buses 80, 81 and 82 in order to energize the individual switch control relays Z to positions corresponding to the positions required for the track switches for that route. Although each track switch is provided with the same control apparatus, it is thought to be sufficient for an understanding of the operation of the system of the present invention to describe the control of

the track switch 7TS by the switch machine control relay 7Z.

With reference to Fig. 4 of the accompanying drawings, the switch control relay 7Z and its control bus 80 has been repeated therein instead of carrying the circuits which it controls by contacts 85 and 86 across from Fig. 1.

Also, that portion of the miniature track diagram illustrated in Fig. 1 of the accompanying drawings which is representative of the track layout associated with the track switch 7TS, has been repeated in Fig. 4 so as to illustrate the control of the miniature track switches by the switch control relays Z.

More specifically, the miniature track switch 7TS is illustrated as controlled by a point indicator 7PI having normal and reverse operating coils N and R which operate an armature 170 to normal and reverse positions respectively. This armature 170 is pivoted at its right hand end and suitably transmits its motion to the miniature switch point 7ts through a connection 171. The normal coil N of the point indicator 7PI is energized by reason of the contact 165 of the switch control relay 7Z being in a normal right hand position, but whenever the contacts of the relay 7Z are operated to left hand reverse positions the contact 165 of course closes a circuit for the reverse coil R of the point indicator 7PI, as will be obvious. In other words, each miniature track switch point indicates the position of its switch control relay.

With this understanding of the operation of the miniature track switch points, it may be seen with reference to Fig. 1 that the operation of the route buttons RB at the two opposite ends of a route cause all of the miniature track switch points to immediately assume positions in accordance with the proposed route even before such route is actually established over the track layout in the field. This provides that the operator is informed immediately as to whether or not it is the route he contemplated, and if it is not he can then quickly rectify any mistake.

It is thus seen, that although the operator sets up his routes and considers them in terms of complete routes, the controls thus effected by the operator are differentiated into the functions of the route so that the operator may check the individual functions in the event that it is necessary to do so in the failure of an individual function to respond. This will be more readily understood after further description of the switch control has been considered.

Associated with the relay 7Z is a lock repeating relay 7LP of the double winding neutral type which is provided with slow releasing characteristics but is quick to pick up. This relay 7LP has contacts 87 and 70. Associated with the miniature track switch 7TS is a lock indicator lamp 71 which is controlled by the back contact 70 of relay 7LP to indicate, when illuminated, that the associated track switch is locked and will not be operated in response to the setting up of new controls.

The position of each track switch is indicated in the central office by a switch repeating relay, which for the track switch 7TS is illustrated as relay 7WPP having contacts 88, 167 and 168. The position of the switch control relay 7Z is indicated on the control panel by the position of the miniature track switch point, but whether the actual track switch 7TS is in a corresponding position or not is indicated by a correspondence indicator 169, which is illuminated whenever the 75

track switch is out of correspondence with its switch control relay 7Z or whenever such track switch is unlocked. With the polar contacts 166 and 167 of the relays 7Z and 7WPP in corresponding positions it is obvious that there is no potential applied to front contact 168 of the relay 7WPP, but whenever these contacts are out of correspondence, positive potential (+) is applied to front contact 168 which energizes the indicator 169, thereby indicating the lack of correspondence between the control relay 7Z and the actual track switch 7TS although it is locked. Whenever the track switch is unlocked, back contact 168 of relay 7WPP is closed and applies potential from (+) to the indicator 169 directly.

These devices 7Z, 7LP and 7WPP are preferably located in the control office adjacent to the switch control relay 7Z, while the switch control is transmitted from the central office to the field station 20 over a line wire 38 forming a circuit with a common return line wire (not shown but indicated by the symbol CN previously explained), and also, the position of the track switch is transmitted over a line wire 39 employed in connection with 25 the common return wire (not shown but indicated by the symbol CN previously explained) to control the indicating relay 7WPP.

At the field station, the position of the track switch and its locked condition is indicated by the 30 usual polar-neutral relay 7WP which is energized with positive or negative energy depending upon whether the track switch 7TS is in a normal or reverse position respectively and is locked, and this relay is deenergized whenever the track 35 switch 7TS is unlocked or is being operated by its switch machine 7SM. This polar-neutral relay 7WP has contacts 95, 96, 97 and 98. The contacts 97 and 98 serve to energize the line wire 39 with positive or negative potential to control the 40 relay 7WPP, as previously mentioned.

The control for the switch machine, as received over the line wire 38, is repeated by a switch control relay 7WZ, which is of the polar-neutral type. This relay is provided with contacts 91, 92, 93, 94, 45 99 and 100. Contacts 93 and 94 of relay 7WZ in combination with contacts 95 and 96 of relay 7WP serve to control two correspondence relays 7NCR and 7RCR to indicate when the track switch is in correspondence with the switch control relay 7WZ.

Associated with the relay 7WZ is a lock relay 7L of the slow release quick pick-up neutral type, the control of which is described more specifically in connection with Fig. 5, it being sufficient at 55 present to understand that this relay is deenergized whenever a route is cleared over the track switch 7TS.

As the operation of such switch control has been more specifically described in my co-pending application Ser. No. 540,596, filed May 28, 1931, and certain features of which have been previously disclosed in the application of R. M. Phinney, Ser. No. 539,486, filed May 23, 1931, it is believed to be sufficient for an understanding of 60 the operation of the present invention to state that the polar contacts 85 and 86 of the relay 7Z take the place of the manually operable control lever in my prior application, Ser. No. 540,596 and apply positive or negative potential from 65 (B+) or (B-) to the control circuit of relay 7WZ whenever the relay 7Z is operated to a new position out of correspondence with the position of polar contact 88 while the lock relays 7L and 7LP are both energized. If such operation of the 70 relay 7Z occurs while the lock relays are de-

energized, then the relay 7LP will not be again picked up until the contacts of the relay 7Z are returned to positions corresponding with the polar contact 88 of the relay 7WPP. This arrangement provides what is termed "the electric lock equivalent" or "the electric lever lock equivalent", so as to prevent what is termed "preconditioning", that is, the setting up of a new route after a train has accepted a first set up route so as to provide that the new route will be automatically set 10 up upon the passing of the train beyond the limits of the first set up route.

In other words, the front contact 87 shunts out the contact 88 when the lock relays are picked up so that the relay 7WZ can receive an opposite 15 potential when the contacts 85 and 86 are out of correspondence with the contact 88, and such reversal does not drop the relay 7LP as its windings are differentially connected.

Whenever the lock relay 7L is deenergized, the 20 contacts of the relay 7WZ are maintained in positions to which they were previously actuated by a stick circuit including polar contacts 91 and 92 of relay 7WZ and back contacts 89 and 90 of 25 relay 7L.

It will be apparent from an inspection of the drawings that the relay 7NCR is normally energized with the relay 7WZ in correspondence with relay 7WP by reason of a circuit closed from (B+), through a circuit including front contact 96 of relay 7WP, polar contact 95 of relay 7WP in a right-hand position, windings of relay 7NCR, polar contact 94 of relay 7WZ in a right-hand position, front contact 93 of relay 7WZ, to 30 (-).

When the route buttons in the control office are so actuated as to cause the polar relay 7Z to assume a reverse position with polar contacts 85 and 86 in their left-hand positions, and the lock relays 7L and 7LP are energized at that time, 40 then the contacts of the relay 7WZ assume reverse positions and the switch machine 7SM responds by reason of the reversal of polarity by 45 polar contacts 99 and 100.

Such reverse operation of the switch machine 45 7SM operates the track switch 7TS to a reverse locked position, which is indicated by the opposite energization of the relay 7WP. This causes the reverse correspondence relay 7RCR to be energized by a circuit closed from (+), through a 50 circuit including front contact 96 of relay 7WP, polar contact 95 of relay 7WP in a left-hand position, windings of relay 7RCR, polar contact 94 of relay 7WZ in a left-hand position, front contact 93 of relay 7WZ, to (-).

It is obvious that both correspondence relays will be deenergized whenever the switch machine is in operation because of open front contact 96; will be deenergized whenever there is a lack of 55 correspondence between the relays 7WZ and 7WP; and, also will be deenergized whenever the relay 7WZ is deenergized.

The control of the switch machine 7SM by the polar contacts 99 and 100 of relay 7WZ may be of any suitable type, such for example as shown 60 in the application of C. S. Bushnell, Ser. No. 408,991, filed November 11, 1929. In other words the switch machine of Patent No. 1,466,903 may be controlled directly by contacts 99 and 100, or modified by the motor control of the above mentioned application Ser. No. 408,991, or any other suitable control for the switch machine motor 65 may be provided.

Emergency switch control.—With reference to Fig. 6 of the accompanying drawings, a manually 70

operable three-position lever with a normal central position is illustrated, which lever may be inserted at the point in the switch control bus 80 indicated by the reference character 83 and its lead line of Fig. 4. The insertion of such a manually operable lever serves at least two purposes, namely, the operator can either control the track switches without the setting up of a route upon the miniature track diagram by the operation of the route buttons RB, or he can use the route buttons to control the signals and use the manually operable levers to set up the switch positions of an optional route. This of course assumes that each of the switch control relays Z is provided with such an emergency manually operable lever, as lever 84.

This independent control for the track switch 7TS, for example, is accomplished by the application of positive or negative potential from (B+) or (B-) to the switch control bus 80 with the lever 84 in left hand or right hand positions respectively, thereby disconnecting the bus 80 from the control of the governing route relays such as relays 40-50 and 40-60 and independently energizing the switch control bus 80. Such control of the manually operable lever 84 must be accomplished while all route relays, such as relays 40-50 and 40-60, are deenergized. Otherwise the lock relays 7L and 7LP would be deenergized and prevent such control.

It may be well to note in this connection, that the lock indicator 7I is energized whenever the track switch 7TS is locked against operation so that the operator will know when the switch is locked. Such an indicator is associated with each miniature track switch located on the diagram so that whenever the operator desires to set up a route, he scans that route to see whether any of the lock indicators for that route are illuminated, and if so he does not endeavor to set up such new route until all such indicators are extinguished. This obviates the penalty of getting a switch control relay Z out of correspondence with its track switch at a time that a lock relay is deenergized, although the lock repeating stick relay 7LP prevents any undesired results in the event that such warning is not heeded.

Thus, the operator can operate the switches independently of route control buttons when such routes as include those switches are at stop and are unoccupied. This provides that the switch can be freed from snow and ice, or the like.

If the operator desires to set up an optional route not controllable by the route buttons, he first operates the manually operable emergency switch control levers, and then positions the route buttons at the ends of the route for the proper direction of traffic movement. The signal for such route clears only after the route indicating circuits in the field (later explained) check the actual establishment of such route.

This independent manual control can also be used to restore a switch control relay Z into correspondence with its switch position indicating relay WPP in the event the warning of a lock light is not heeded, and the route control of a switch is lost. As the correspondence lamps or indicator, such as indicator 169, are normally dark, and are only temporarily illuminated while their switches are in transit, a continuously illuminated correspondence lamp serves to advise the operator as to what switch control relay Z needs to be returned into correspondence with its track switch.

75. *Route interlock.*—With reference to Fig. 3 of

the accompanying drawings, the track lay-out, signal and switch arrangement is repeated from Fig. 2 for convenience in the consideration of this figure with respect to the circuit selections. The correspondence relays 7NCR and 7RCR illustrated in Fig. 4, above considered, have been shown in block form in Fig. 3, associated with the lock relay 7L, so that the route circuits selected by these three relays may be illustrated. Although only the control circuits for the relays 7NCR, 7RCR and 7L are specifically illustrated in the drawings, it is to be understood that similar control circuits are provided for the correspondence and lock relays for the other switches. Thus, the relays 45NCR, 45RCR, 45L, 23NCR, 23RCR and 23L have been illustrated only in block form instead of showing the circuits which control them.

The relays 7L, 7NCR and 7RCR are provided with contacts 133, 134 and 135 respectively for 20 selecting route circuits. Similarly, the relay 23L is provided with contacts 116 and 122; the relay 23RCR with contact 127; the relay 23NCR with contacts 117 and 123; the relay 45NCR with contacts 118 and 124; the relay 45RCR with 25 contact 128; and, the relay 45L with contacts 119 and 125.

Figs. 1 and 3 may be placed end to end so that the signal control bus wires of the two figures connect together. In other words, Fig. 2 placed 30 end to end to Fig. 1 indicates by dotted lines the ultimate destination of the signal control wires, while Fig. 3 placed end to end with Fig. 1 illustrates the detail control provided in connection with the signal control buses. 35

Each signal control bus ends in a signal control relay GZ which is indicated as associated with its respective signal by reason of like preceding numerals.

More specifically, a signal control relay 10GZ is 40 connected in the signal control bus 78 and is illustrated as having contacts 101, and 115 in this figure of the drawings, although it is to be understood that it is to have additional contacts for the selection of the signal control circuits and lock relay control circuits in a similar manner as illustrated specifically for a signal control relay 40EGZ in Fig. 5 of the accompanying drawings, later to be considered. Similarly, a signal control relay 20GZ is provided with contacts 103 45 and 121; a signal control relay 30GZ is provided with contacts 105 and 120; a signal control relay 40WGZ is provided with contacts 107, 126 and 132; a signal control relay 40EGZ is provided with contacts 109, 130 and 131; a signal control relay 50 50GZ is provided with contacts 111 and 137; a signal control relay 60GZ is provided with contacts 113 and 136.

Associated with each of the signal control relays GZ and their respective signals is a suitable 60 route indicating relay RR which indicates whenever a route is established over which its associated signals govern traffic. These route indicating relays RR are provided with contacts, in addition to those illustrated in Fig. 3, for the 65 purpose of selecting signal circuits, and the like, so that the contacts illustrated with the route indicating relays RR in Fig. 3 are only those that are necessary for the controls illustrated therein.

More specifically, a route relay 10RR is associated with signal 10 and is provided with contact 102; a route relay 20RR is provided with contact 104; a route indicating relay 30RR is provided with contact 106; a route relay 40WRR is provided with contacts 108 and 129; a route 70 75

indicating relay 40ERR is provided with contacts 110 and 164; a route indicating relay 50RR is provided with contact 112; a route indicating relay 60RR is provided with contact 114. These signal control relays GZ and route relays RR are of the usual neutral type relay.

Under the heading "Establishing a route", it was considered how a route is established from the signal 20 to the signal 40 by the proper positioning of the route buttons 20RB and 40RB, but only the general results obtained were considered subsequent to the energization of the switch control buses and signal control bus. However, it is now desired to consider more in detail the operations involved in the establishment of this route following the energization of the switch control buses and the signal control bus for such route.

As soon as the route relay 20-40 is picked up, the contacts 36 and 37 apply (B+) to the switch control buses 81 and 82 thereby actuating the polar contacts of the relays 45Z and 23Z respectively to their normal right hand positions, if they are not already in such positions. Such actuation of the relays 45Z and 23Z causes the control of their respective switch machines and track switches in a manner similar to that pointed out more specifically in connection with the track switch 7TS.

As the track switches are considered to be unlocked at this time, and the relays Z having been in correspondence with their relays WPP, the switch controls are transmitted to the WZ relays and thence to the switch machines. Such control is transmitted to the WZ relays only while the lock relays L are still energized, that is, are dropping away subsequent to the opening of their energizing circuits. As the lock relays are made slow releasing, there is provided sufficient period of time in which the relays WZ may respond, although the lock relays 23L and 45L are deenergized upon the picking up of the signal control relay 20GZ. The signal control bus 77 is energized simultaneously with the energization of the switch control buses by a circuit closed from (B+), through front contact 33 and polar contact 34 of the route relay 20-40, signal control bus 77, windings of the relay 20GZ, back contact 104 of the route indicating relay 20RR, to (CN). As soon as relay 20GZ responds, it closes its front contact 103 rendering it entirely dependent for its energization upon the route relay 20-40, so that upon the actual establishment of the route and the indication of such establishment by the energization of the route indicating relay 20RR and the opening of back contact 104, the relay 20GZ will still remain energized.

The manner in which the relay 20GZ opens the energizing circuits for the lock relays 23L and 45L may be seen by analogy to Fig. 5, later to be explained, wherein it is shown that the lock relay 7L is deenergized whenever a relay GZ governing traffic over its track switch is picked up.

As soon as the lock relays are deenergized and the track switches have come into correspondence with their WZ relays as indicated by their correspondence relays NCR and RCR, then a route circuit is completed for the route indicating relays 20RR and 40WRR closed from (+), through a circuit including front contact 121 of relay 20GZ, windings of relay 20RR, back contact 122 of relay 23L, front contact 123 of relay 23NCR, front contact 124 of relay 45NCR, back contact 125 of relay 45L, windings of relay 40WRR, back contact 126 of relay 40WGZ, back contact 164 of relay 40ERR, to (-).

As soon as the relays 20RR and 40WRR respond, a stick circuit is completed including front contact 129 of relay 40WRR so as to eliminate the control of the relay 40ERR, as such relay is energized whenever the route is completed between the signal 40 and either the signal 50 or the signal 60.

When a route is set up from the signal 40EA to the signal 50, the relays 40EGZ and 40ERR are picked up, so that the route indicating circuit, just traced above, can be completed at any time nor is it broken by the clearing of signal 40EA. But when the signal 40EA is put to stop by the deenergization of the relay 40EGZ, the contacts 131 and 164 open sequentially in that order and the stick contact 129 prevents the deenergization of relays 40WRR and 20RR.

On the other hand, if a route is set up from signal 50 to the signal 40WA, the relay 40ERR is picked up while the relay 40EGZ is deenergized. This causes the route circuit for relays 20RR and 40WRR to be maintained open at back contact 164. This prevents the opposing signals 20A and 50 from being cleared at the same time. It is of course seen that if the signal 20A were cleared first, the signal 50 would be prevented from being cleared by reason of open back contact 129.

Let us assume that the operator desires to continue the route from the signal 40 to the signal 50, as considered under the heading "Establishing a route." The switch control relay 7Z is actuated to its normal position following the positioning of the route buttons RB, which relay 7Z controls the relay 7WZ to the normal position, in a manner previously described, so that the track switch 7TS assumes a normal position in correspondence with the relay 7WZ. Also, the energization of the signal control bus 73 causes the relay 40EGZ to be energized through a circuit including back contact 110 of relay 40ERR and upon its picking up closing front contact 109, so that the control of relay 40ERR by contact 110 is eliminated.

The energization of the relay 40EGZ opens the energizing circuit of the lock relay 7L, which is shown in Fig. 5 as a circuit closed from (+), through a circuit including back contact 149 of relay 60G, back contact 150 of relay 60GZ, back contact 151 of relay 50GZ, back contact 152 of relay 40EAG, back contact 153 of relay 40EBG, back contact 154 of relay 40ECG, back contact 155 of relay 40EGZ, front contact 156 of track relay 7T, back contact 157 of relay 50G, windings of the relay 7L, to (-).

Although the switch bus 80 is energized simultaneously with the signal bus 73, the relay 7WZ has plenty of time to actuate its contacts to their proper positions as relay 7L is slow releasing, previously mentioned. With the relay 7L deenergized and the relay 7NCR energized because the track switch 7TS is in normal position in correspondence with the relay 7WZ, a route circuit is completed for the route indicating relays 40ERR and 50RR from (+), through a circuit including front contact 130 of relay 40EGZ, windings of relay 40ERR, back contact 133 of relay 7L, front contact 134 of relay 7NCR, windings of relay 50RR, back contact 137 of relay 50GZ, to (-). The picking up of relay 40ERR opens back contact 110 and back contact 164, but as the relay 40WRR is picked up, its front contact 129 maintains itself energized to its selected route circuit, and also the closure of contact 109 eliminates the control of contact 110 for the relay 40EGZ. The energization of the relay 50RR opens its back

contact 112 preventing improper control of the relay 50GZ.

With the route circuits thus established, the respective signals are cleared, that is, with the 5 relays 20GZ and 20RR energized, with the track switches 2TS, 3TS, 4TS and 5TS in normal positions, the signal 20A is cleared; while with the relays 40ERR and 40EGZ energized with the track switch 7TS in a normal position, the signal 40EA 10 is cleared. Although control circuits have not been shown for signal 20A, it is to be understood they are similar to those specifically illustrated in connection with the control of signal 40EA in Fig. 5 of the drawings and explained under "Signal 15 selection." It is to be understood that similar signal control circuit selections are made in connection with each of the signals of the track layout.

It is believed that the control of the various 20 other route circuits will be readily apparent from the consideration of the route circuits already pointed out, it being sufficient for further understanding of such route circuits to merely point out the completion of certain typical ones.

25 For example, let us consider the route circuit closed when it is contemplated to clear the signal 30B to allow the passage of traffic over the crossover including track switches 2TS and 3TS to the signal 20. Under such circumstances the 30 signal control relay 30GZ is picked up, which closes the route indicating circuit for the route indicating relays 30RR and 20RR from (+) through a circuit including front contact 120 of relay 30GZ, windings of relay 30RR, back contact 119 of relay 45L, front contact 118 of relay 45NCR, front contact 127 of relay 23RCR, back contact 122 of relay 23L, windings of relay 20RR, back contact 121 of relay 20GZ, to (-). The 40 manner in which the relays 30GZ and 30RR clear the signal 30B will be readily understood by analogy of the description given with regard to the clearing of signals in Fig. 5.

It is also desired to point out, that the optional route over the track switches 2TS, 3TS, 4TS 45 and 5TS in reverse positions is provided with a route indicating circuit, although the route buttons RB do not themselves cause the switches to assume such positions but rather the operation of the individual manually operable emergency control levers, as previously mentioned. For example, assuming the signal 20B is to be cleared for the passage of traffic over such optional route, the relay 20GZ is energized by the positioning of the route buttons 20RB and 40RB to the right following the positioning of the manually operable emergency switch control levers, such as lever 84, (see Fig. 6). With the relay 20GZ picked up, and the switches in their proper positions as 60 indicated by the correspondence relays 23RCR and 45RCR, a route indicating circuit is closed from (+) through a circuit including front contact 121 of relay 20GZ, windings of relay 20RR, back contact 122 of relay 23L, front contact 127 of relay 23RCR, front contact 128 of relay 45RCR, back contact 125 of relay 45L, windings of relay 40WRR, back contact 126 of relay 40WGZ, back contact 164 of relay 40ERR, to (-). The response of the relays 20RR and 40WRR closes the front contact 129 of relay 40WRR which eliminates the check that back contact 164 of relay 40ERR provides to insure that the signals 50 and 60 are at stop. The manner in which the signal 20B is cleared upon the energization of the relays 20GZ and 20RR will be readily apparent 75

by analogy of the description given with regard to Fig. 5.

It is desired to again point out that no indicating route circuit can be completed for route indicating relays RR until the track switches are in 5 correspondence with their respective relays WZ in spite of the fact that their respective lock relays L may be deenergized as soon as the signal control relays GZ receive energization.

In this connection under the heading "Route 10 interlock" it is desired to point out that such route indicating circuits provided to indicate when a route has been established, are disclosed and claimed in my prior application, Ser. No. 540,596, filed May 28, 1931, and in the application of Larry 15 and Langdon, Ser. No. 577,504, filed Nov. 27, 1931, the present disclosure being made for the purpose of showing the interrelation between such route indicating circuits and the features of the present invention, it also being understood that these new 20 relationships between the control provided by the present invention and the route circuits thus shown herein are intended to be claimed in this application.

Signal selections.—Referring to Fig. 5 of the 25 accompanying drawings, that portion of the track lay-out including the track switch 7TS has been repeated for convenience in considering the circuits shown in Fig. 5. The signal control relays 40EGZ, 50GZ and 60GZ have been repeated from 30 Fig. 3 and shown in block form for convenience in showing certain circuits which they control. Similarly, the route indicating relays 40ERR, 60RR and 50RR have been likewise repeated from Fig. 3 and shown in block form. The correspondence relays for the track switch 7TS, namely, relays 1NCR and 1RCR have been repeated from Fig. 4 to illustrate their control in the signal circuits. Also, track relays 7T, 8T and 9T, indicated in Fig. 2 of the accompanying drawings, 40 have been repeated for convenience.

In addition to those relays which have been repeated from other figures of the drawings, signal relays G have been shown, there being one for each signal arm with its reference character containing a G preceded by the reference character of its associated signal. In other words, each signal is provided with a control relay G of the neutral type which when de-energized causes the red indicator R to be illuminated, and which 45 when energized causes the green or clear indicator G to be illuminated. In this connection, it is to be understood that if home and distant relays are employed that green and yellow indications may be provided in accordance with the 50 usual practice but such control has not been illustrated for the purpose of making the disclosure as simple as possible.

We will now consider how the signal 40EA is 60 cleared following the energization of the relay 40ERR. As the relay 40EGZ is energized with positive potential from (B+) through front contact 62 of relay 40—50, over signal control bus 73, the polar contacts of the relay 40EGZ assume right hand positions. With the track switch 7TS 65 in a normal position, the energizing circuit for the signal relay 40EAG is then closed from (+), through a circuit including front contact 138 of relay 40ERR, front contact 139 of relay 40EGZ, polar contact 140 of relay 40EGZ in a right hand 70 position, front contact 141 of track relay 7T, front contact 142 of track relay 8T, front contact 143 of relay 1NCR, windings of relay 40EAG, to (-).

As soon as the relay 40EAG picks up, the red indicator of the signal 40EA is de-energized by 75

reason of the opening of back contact 158, and the green indicator is energized by reason of the closure of front contact 158. With the signal thus cleared, the train may proceed in accordance therewith.

In a similar manner the relay 40EBG controls the signal 40EB by contact 159; the relay 40ECG controls the signal 40EC by contact 160; the relay 69G controls the signal 60 by contact 148; the signal relay 50G controls the signal 50 by contact 161.

It is of course obvious, that if the track switch 7TS is operated to a reverse position by reason of the actuation of the route button 60RB instead of the actuation of the route button 50RB, then the relay 40EAG would not be energized but the relay 40EBG would be energized by reason of the energization of the relay 7RCR instead of the relay 7NCR.

For example, the circuit for relay 40EBG would then be closed from (+), through a circuit including front contact 138 of relay 40ERR, front contact 139 of relay 40EGZ, polar contact 140 of relay 40EGZ in a right hand position, front contact 141 of relay 7T, front contact 144 of relay 9T, front contact 145 of relay 7RCR, windings of relay 40 EBG, to (-).

For the purpose of simplicity in the drawings, the signal relays 50G and 60 G have not been illustrated as being provided with track circuit control or other selections. Thus, the relay 50G is controlled only by the relays 50GZ and 50RR so that when the contacts 162 and 163 of these relays respectively are closed, the relay 50G is energized and the signal 50 is cleared. This of course can occur only when the route is established in the opposite direction from that above explained by reason of the actuation of the route buttons 50RB and 40RB to the left.

Similarly, the signal relay 60G is energized when the relays 60GZ and 60RR are picked up to close their respective contacts 147 and 146, when the route buttons 60RB and 40RB are actuated to the left.

It was pointed out under the heading "Call-on control," that the energization of the signal control bus 73 with negative potential from (B-), through front contact 69 of the relay 40ECS, caused call-on signal 40EC to clear. It can now be seen that such energization of the signal control bus 73 causes the relay 40EGZ to actuate its polar contact to left hand positions (see Figs. 3 and 5) which causes the energization of the relay 40ECG (see Fig. 5) instead of either of the relays 40EAG or 40EBG. This energizing circuit is closed from (+), through a circuit including front contact 138 of relay 40ERR, front contact 139 of relay 40EGZ, polar contact 140 of relay 40EGZ in a left hand position, windings of relay 40ECG, to (-). It is seen that this energizing circuit for the relay 40ECG, which controls directly the signal 40EC, is independent of track circuit control and such call-on signal control is used only when the upper arm signals 40EA and 40EB are not capable of being cleared by reason of trains in advance of such signals.

Although only the signal relays GZ and G with the track relays T have been shown as controlling the lock relay 7L, it is to be understood that any other suitable usual selections may be inserted, such as the use of directional tumble-down stick relays as shown and described in the application of Stoltz, Ser. No. 402,527 filed October 25, 1929, together with features of approach and release

route locking. This has been omitted for the sake of simplicity.

Modified control panel.—With reference to Fig. 8 of the accompanying drawings, the control panel of Fig. 1 and the route circuits shown there-⁵ in are modified by the provision of a different type of route button. This provides that the establishment of a route requires the actuation of the route buttons at the two opposite ends of such route, but the returning to stop of such route requires the restoration of only the route button corresponding to the signal which cleared for that route, as the route button at the opposite end of such route is automatically restored to normal following its actuation.

The same miniature track diagram is repeated for convenience having the same miniature track switch points and corresponding to the track layout illustrated in Fig. 2. The route buttons RB and their respective contacts have been given the same reference characters with distinctive ex-¹⁰ponents as assigned in Fig. 1 of the accompanying drawings as each of these route buttons are of a different structure than that contemplated in Fig. 1. Also, the arrangement of route buttons 20 for the double signal location 40, as described in connection with Fig. 7, has been applied to this modified form.

Each of these route buttons comprises a structure more specifically disclosed in Figs. 9 and 10 ³⁰ of the accompanying drawings to which reference should now be made to obtain an understanding of the operation of these buttons before considering the general operation and control of the route circuits and relays.

Referring to Figs. 9 and 10, a route button, such as route button 10RB², has been shown in detail. Such a route button is mounted upon a panel 220, and includes a shaft 221 which passes through the panel and which can be manually rotated by grasping a knob 222.

On this shaft 221 is a collar 223 which has mounted therein a pin 224. The collar 223 can be adjustably fastened to the shaft 221 by a set screw 225 to thereby be rotated when the shaft 45 221 rotates.

A lever 226 is mounted on the shaft 221 in a manner to freely rotate except as engaged by the pin 224 of the collar 223. This lever is held in place on the shaft to engage the pin 224 by a 50 collar 227 which is pinned to the shaft.

A fixed stop 228 is located on one side or the other of the movable lever 226 depending upon whether the button is to be biased in one direction or the other, and the lever 226 is biased 55 against this stop 228 by a spring 229. The spring 229 is pivotally attached to the lever 226 at one end and is suitably attached to a fixed point at the other end, which fixed point is suitably chosen with regard to the fixed stop 228 so as to provide 60 a continual bias on the lever 226. The button illustrated has been chosen as what may be termed a left hand biased button illustrated in Fig. 8 as the button 10RB² for example, as such button is caused to be biased away from its left 65 hand position. Thus, the stop 228 is to the right of the lever 226 as viewed in Fig. 10 which is a sectional view taken on line 10—10 of Fig. 9 looking in the direction of the arrows. Also, the pin 224 of the collar 223 is adjusted to be on the right 70 of the lever 226. Thus, as the route button 10RB² is rotated to the right (as viewed in Fig. 8), the collar 223 rotates counterclock-wise (as viewed in Fig. 10) so that the pin 224 does not engage the lever 226. This allows the knob 222 75

and the contact arms, such as arm 230, to remain in their last operated positions.

On the other hand, if the knob 222 is rotated counter-clock-wise (as viewed in Figs. 8 and 9) the pin 224 engages the lever 226 and causes the spring 229 to stretch. Thus, as soon as the operator ceases to grasp the knob 222 the tension of spring 229 causes the lever 226 to engage the pin 224 and rotate the shaft 221 and its associated contact levers, such as lever 230, to their normal positions until the lever 226 engages the stop 228.

It is obvious that as many contact arms may be connected to the shaft as desired and each made independent of the other by suitable insulating materials all of which may be constructed in any desired manner. It is sufficient for an understanding of the present invention to know that when the knob 222 is rotated in either direction for a sufficient angle, such as 90° for example, contacts are made so as to complete such circuits as might be desired.

In Fig. 8, the route buttons have been illustrated conventionally so that each contact is indicated as having a spring bias in a particular direction with suitable stops as just described in connection with Figs. 9 and 10, but the conventional should be considered as a sectional view looking from the knob toward the back (see Fig. 9) instead of on the line 10—10 in the direction of the arrows. This gives corresponding rotational relationships between the knobs and the contacts. Also, biasing means has been shown for each contact of a route button instead of showing a single bias for one route button as would probably be employed in practice. This is done so that the relation of the stops and the direction of bias for each contact will be readily apparent.

The same route relays illustrated in Fig. 1 have been repeated in this Fig. 8 and are shown as included in the same route circuits, the only difference being that each of these relays is provided with two additional contacts to provide for stick circuits hereinafter more specifically discussed. Each of these route relays, such as relay 10—30 for example, is considered to have the same contacts as shown in Fig. 1, such as contacts 52, 53, 54 and 55, for controlling the energization of the signal and switch control buses.

More specifically, the route relay 10—30 is provided with additional contacts 180 and 181; the route relay 20—30 with contacts 182 and 183; the relay 10—40 with contacts 184 and 185; the relay 20—40 with contacts 186 and 187; the relay 40—50 with contacts 188 and 189; the relay 40—60 with contacts 190 and 191.

Associated with each of the route button controlling contacts is a suitable resistor which prevents the shorting of the battery source, as more specifically pointed out hereinafter. Thus, a plurality of resistors are provided and include resistors 192, 193, 194, 195, 196, 197, 198, 199, 210, 211, 212 and 213.

It is to be understood, that those features pointed out in connection with Fig. 1 of the accompanying drawings which are not specifically pointed out in connection with Fig. 8 as being different, are considered to be similarly associated with this modified structure of control. For example, it was pointed out in connection with Fig. 1 that each of the miniature track switch points has associated therewith a suitable lock light as described in connection with Fig. 4 of the accompanying drawings. All such

characteristic features will not be further considered.

Consideration will now be given to the novel manner in which the routes are established. For example, let us assume that the operator desires to establish a route from the signal 20 to the signal 40 by clearing the signal 20A. To do this, the operator actuates the route button 20RB² to the right in which position it remains, and following which the operator actuates the route button 40RBW² to the right, but which button returns to its normal position as soon as the operator removes his hand.

During the contemporaneous actuation of the route buttons 20RB² and 40RBW², a pick up circuit is closed for the route relay 20—40 from (+), through a circuit including resistor 195, contact 222 in a right hand position, back contact 26 of relay 20—30, back contact 27 of relay 10—40, windings of relay 10—40, contact 422 in a right hand position, to (—).

This energization of the relay 20—40 causes its polar contact 187 to assume a right hand position and its neutral contact 186 to be picked up, which thereby completes a stick circuit for the relay 20—40 from (+), through a circuit including resistor 195, contact 222 in a right hand position, back contact 26 of relay 20—30, back contact 27 of relay 10—40, windings of relay 10—40, polar contact 187 of relay 20—40 in a right hand position, front contact 186 of relay 20—40, to (—).

As the relay 20—40 is thus energized through its stick circuit, the contact 422 may return to its normal position automatically in accordance with its structure as above described, but the relay 20—40 remains energized wholly dependent upon the manual return of the route button 20RB to a normal position.

The energization of the relay 20—40 and the actuation of its polar contacts to positions in accordance with the direction of the actuation of the route buttons 20RB² and 40RBW², causes the switch machines 2SM, 3SM, 4SM and 5SM to be controlled in accordance with the required normal positions for main line traffic after which the signal 20A is cleared, all of which has been described in connection with Figs. 1, 2, 3, 4 and 5.

It is obvious, that if the route buttons 20RB² and 40RBW² are actuated to the left for the establishment of a route in that direction, the contacts of the route button 40RBW² will be the ones to remain in their actuated positions while the contacts for the route button 20RB² will be the ones to return to their normal positions.

In such a case, the route circuit would be energized by a circuit closed from (+), through a circuit including resistor 199, contact 422 in a left hand position, windings of relay 20—40, back contact 27 of relay 10—40, back contact 26 of relay 20—30, contact 222, to (—).

Such an energization of the relay 20—40 causes its polar contacts to operate to the left and its neutral contacts to be picked up. This closes a stick circuit for the relay 20—40 from (+), through a circuit including contact 422 in a left hand position, windings of relay 20—40, polar contact 187 of relay 20—40 in a left hand position, front contact 186 of relay 20—40, to (—). This stick circuit then causes the relay 20—40 to be wholly dependent upon the manual restoration of the route button 40RBW².

It is apparent from the above description that each of the route relays is provided with a pick up circuit corresponding to its energizing circuit

pointed out in connection with Fig. 1. But in addition to such pick up circuit, a stick circuit is provided which eliminates the control of the route button at the end of the route being established following the response of the route relay for such route. Thus, as such route button at the end of the route automatically returns to its normal position following its actuation when the operator removes his hand from the button, then only the route button at the entrance of the route need be returned in order to put such route to stop and release the track switches included therein.

It is believed that each of the different pick up and stick circuits will be readily understood by considering the description in connection with this figure and preceding figures, without specifically pointing out each of the route circuits established for each of the combinations possible with the track layout illustrated. However, it is desired to point out that the spring bias and stop arrangement for each of the route buttons must be arranged so as to automatically cause the route button to return to normal when such route button is turned in a direction representative of the exit end of the route with which it is associated, but when turned in the opposite direction representative of the entrance end of the route with which it is associated it must then remain at such actuated position until manually restored. With this construction of route button, it therefore becomes necessary to provide two route buttons such as route buttons 40RBW² and 40RBE² at a double signal location, all of which has been discussed in connection with Fig. 7 of the accompanying drawings.

This arrangement not only has the advantage that only the route button RB at the entrance of a route must be returned in order to put such route to stop, but also has the advantage that should the operator forget the route button at the exit end of a route, that an erroneous route is not subsequently set up in the setting up of other routes.

For example, if the route from the signal 20 to the signal 40 is established and a train is in such route, while another train is approaching the signal 10A, the operator may desire to put the signal 20A to stop and cause the signal 10A to be cleared. To do this he might return the route button 20RB² to normal but fail to return the route button 40RBW² (assuming it to not be automatically restored) so that when the route button 10RB² is actuated, an undesired route over the crossover including the track switches 4TS and 5TS would be established. But in accordance with the system of Fig. 8 such a condition cannot be set up as the route button 40RBW², for example, is self-restoring when thus employed to establish a route.

The resistors, such as resistor 199 for example, are provided to prevent the shorting of a battery source while a route relay is picked up upon the accidental or unintended operation of a route button in a direction opposing the route button which controls such route relay. More specifically, if the route button 20RB² is operated to the right followed by the actuation of the route button 40 RBW² to the right, the relay 20-40 is picked up and stuck up, as previously explained. Now suppose the operator accidentally operated the route button 40RBW² to the left, (+) is connected to the opposite terminal of the battery source through polar contact 187 and front contact 186, but as the resistor 199 is of sufficient

value to prevent a short or a substantial change in voltage from the battery source, the relay 20-40 is unaffected, and any dangerous condition is avoided. The resistance value of the resistors must of course be selected in accordance with the voltage employed. 5

Summary

A system of interlocking has thus been shown and described which provides that a route may be established over a track lay-out in the field by the actuation of route buttons on a miniature track diagram in the control office, with the particular direction of traffic movement determined by the joint operation of these buttons in a corresponding direction with regard to the miniature track diagram. In a system of this character, it therefore becomes necessary to establish the signal and switch controls simultaneously, and the control of the individual switches and signals thus simultaneously established is caused to be effective in sequence by reason of time delay inserted in the lock relays. In other words, the switches receive their controls first and are operated but the signals cannot be cleared until the lock relays which allow the switch to be controlled are deenergized and even then the signals do not clear until the switches have been operated into correspondence with their respective control relays which were positioned prior to the dropping 30 away of the lock relays.

Also, it has been shown how individual control for the track switch can be inserted in addition to the route control provided by the route buttons.

An interlock between conflicting routes has been provided in the control office to prevent the erroneous transmission of route controls although an interlock is provided at the field location so as to prevent the clearing of opposing and conflicting routes. It has also been illustrated 40 how automatic traffic control may be inserted into the signal control, as well as the provision of call-on signals in the event that traffic control prevents the clearing of a signal.

Having described an interlocking system as one specific embodiment of the present invention, it is desired to be understood that this form is selected to facilitate in the disclosure rather than to limit the number of forms which it may assume; and, it is to be further understood that various modifications, adaptations and alterations may be applied to the specific form shown to meet the requirements of practice, without in any manner departing from the spirit or scope of the present invention except as limited by the appended claims. 50

What I claim is:—

1. In an interlocking system for railroads, a track layout having a plurality of tracks interconnected by a plurality of track switches to form a plurality of different routes, a plurality of signals for governing traffic through said track layout, a miniature track diagram corresponding to said track layout, a control button on said track diagram for each of said signals and in corresponding positions, contacts operated by each of said control buttons, a route circuit for each of said routes through said track layout and having included therein at its two opposite ends those contacts which are operated by the control buttons which correspond to the two opposite ends of such route, a route relay included in each of said route circuits, switch operating means controlled by each route relay for operating each of said track switches included in its route to a 75

position proper for establishing such route, manually operable means for each track switch for governing said switch operating means for that switch independently of said route relays, signal control means controlled by each of said route relays for clearing the one of said signals governing traffic over such route, and means requiring said switches for a route to respond to their respective switch operating means before said signal control means for that route can be effective.

2. In an interlocking system for railroads, a track layout having a plurality of tracks interconnected by a plurality of track switches to form a plurality of different routes, a plurality of signals for governing traffic through said track layout, a miniature track diagram corresponding to said track layout, a control button on said track diagram for each of said signals and in corresponding positions, contacts operated by each of said control buttons, a route circuit for each of said routes through said track layout and having included therein at its two opposite ends those contacts which are operated by the control buttons which correspond to the two opposite ends of such route, a route relay included in each of said route circuits and energized by the operation of the contacts alone at its opposite ends, switch operating means controlled by each route relay for operating each of said track switches included in its route to a position proper for establishing such route, signal control means controlled by each of said route relays for clearing the one of said signals governing traffic over such route, manually operable means for a certain signal for imposing additional control on its signal control means subject to said route relays governing said signal control means to cause that signal to display a special indication, and means requiring said switches for a route to respond to their respective switch operating means before said signal control means for that route can be effective.

3. In an interlocking system for railroads, a track layout having a plurality of tracks interconnected by a plurality of track switches to form a plurality of different routes, a plurality of signals for governing traffic through said track layout, a miniature track diagram corresponding to said track layout, a control button on said track diagram for each of said signals and in corresponding positions, contacts operated by each of said control buttons, a route circuit for each of said routes through said track layout and normally open contacts at its two opposite ends only, the closing of each route circuit requiring operation of only the two buttons which correspond to the two opposite ends of such route, a route relay for each of said route circuits and included therein, whereby the contemporaneous actuation of said control buttons alone at the two opposite ends of a route causes said relay for that route to be picked up, stick circuit means for each of said route relays arranged to be effective to maintain a particular route relay picked up dependent only upon one of said two buttons required to be actuated to effect the picking up of such route relay, switch operating means controlled by each route relay for operating each of said track switches included in its associated route to a position proper for establishing such route, signal control means controlled by each of said route relays for clearing one of said signals for governing traffic over such route, and means requiring said switches

for a route to respond to their respective switch operating means before said signal control means for that route can be effective.

4. In an interlocking system for railroads, a track layout having a plurality of tracks interconnected by a plurality of track switches, a plurality of signals for governing traffic through said track layout, a miniature track diagram corresponding to said track layout, a control button on said track diagram for each of said signals and in corresponding positions, a single route relay individually appertaining to each desired route through said track layout, circuit means for causing said relay for any desired route to be responsive only to the joint operation of said control buttons at the opposite ends of that route, and means controlled by each of said route relays for automatically controlling the track switches in said track layout to establish that route from one of the corresponding signals to the other and to clear the signal for such route.

5. In an interlocking system for railroads, a track layout having a plurality of tracks interconnected by a plurality of track switches to form a plurality of partly interinclusive routes, a plurality of signals for governing traffic through said routes, a plurality of route relays each belonging individually to a corresponding route, means for controlling certain of said switches by each of said route relays, signal control means for controlling said signals for any route by the corresponding one of said route relays subject to traffic conditions except when specially controlled, and manually operable means for impressing special control on said signal control means for clearing a signal for a route independently of said traffic conditions but dependent upon said route relay for that route.

6. In an interlocking system for railroads, a track layout having a plurality of track switches so arranged as to form a plurality of conflicting and non-conflicting routes between signal locations, a control lever for each signal location at the opposite ends of said routes, each lever having normal and operated positions, a route circuit for each of said routes energized by the joint cooperation of the levers in operated positions for the signal locations at the opposite ends of that route, a route relay individually belonging to a corresponding route and included in each route circuit, each route relay being provided with back contacts for opening all of the remaining route circuits which correspond to conflicting routes, means for operating said track switches to normal and reverse positions as required for any route upon the energization of said route relay for that route, means controlled by said route relay for that route for clearing the signal at the entrance of that route and rendered effective only after all of said track switches in that route are operated to proper positions.

7. An interlocking system of the entrance exit type comprising, a track layout consisting of a plurality of tracks interconnected by track switches to form a plurality of routes, a manually operable control device for each route end, a switch machine for each track switch, a switch control relay means for each switch machine to control the same, a stick relay for each switch machine which if deenergized prevents said relay means controlling its associated switch machine, a signal at each entrance end to a route, a signal control relay for each signal, a lock

- contact for each track switch closed only when it is safe to operate said track switch to a new position, means effective to control all of the switch control relay means for a particular route to establish that route and to energize the signal control relay for the signal governing the entrance of trains into that route upon operation of the manually operable control devices at the ends of that route, and means for picking up 5 the stick relay for a particular switch only if the switch control relay means for that switch and the switch machine for that switch assume corresponding positions and the lock contact for that switch is closed.
- 10 8. In an interlocking system for railroads, the combination with a track layout including track switches operable to positions to establish any one of a plurality of routes each including a plurality of track switches, a manually operable device for each route end having a normal and an actuated position, a switch control relay means for each track switch, switch locking means for each track switch ineffective only when it is safe to operate the switch, means effective to control 15 a plurality of switch control relay means to establish a particular route only if the manually operable device at each end of that route is operated to an actuated position, and means for preventing operation of a track switch in response 20 to a change in its control relay means unless the switch control relay means for that switch was actuated at a time when the locking means for that switch was ineffective.
- 25 9. In an interlocking system for railroads, a track layout forming a plurality of routes with each route including a track switch assuming a normal or reverse position, manually operable devices for the ends of certain routes each of said devices having a normal position and a control 30 position, means effective to operate the track switch for a particular route from its last operated position to normal or reverse position as required to establish that route only when said manually operable devices for the opposite ends 35 of that route are both operated to their control positions, a locking contact for each track switch closed only when it is safe to operate that track switch to a new position, and means for preventing operation of a track switch to establish 40 a particular route unless its associated locking contact is closed at the time the manually operable devices at the ends of that route are both 45 operated.
- 45 10. In an interlocking system for railroads, a track layout forming a plurality of routes with each route including a track switch assuming a normal or reverse position, a signal at each entrance end to a route, manually operable devices for the ends of certain routes each of said devices 50 having a normal position and a control position, means effective to operate the track switch for a particular route from its last operated position to normal or reverse position as required to establish that route and to clear a signal governing 55 the entrance of traffic into said particular route only when said manually operable devices for the opposite ends of that route are both operated to their control positions, a locking contact for each track switch closed only when it is safe 60 to operate that track switch to a new position, and means for preventing operation of a track switch to establish a particular route unless its associated locking contact is closed at the time the manually operable devices at the ends of that 65 route are both operated.
- 70 11. In an interlocking system for railroads, a track layout having a plurality of tracks interconnected by a plurality of track switches to form a plurality of different routes, a plurality of signals for governing traffic through said track layout, a miniature track diagram corresponding to said track layout, a manually operated button on said track diagram for each of said signals and in corresponding positions, contacts operated by each of said buttons, a route circuit for each of 75 said routes through said track layout and normally open at two points only and closed by those of said contacts which are operated by the buttons which correspond to the two opposite ends of such route, a route relay included in each of said route circuits, said route relay for any given route being energized only if both of the buttons for the ends of that route are operated to close the corresponding route circuit, switch operating means controlled by each route relay for operating each of said track switches included in its route to a position proper for establishing such route, signal control means controlled by each of said route relays for clearing that one of said signals governing traffic over such route corresponding to that route relay, and means requiring such switches for a route to respond to their respective switch operating means before said signal control means for that route can be effective.
- 80 12. In an interlocking system; a track layout having track switches so as to form a plurality of certain desired routes for train movement through said track layout, certain of the routes being conflicting and others non-conflicting, a route circuit for each of said routes; a single route relay individually appertaining to each route and included in each route circuit, each route relay being provided with back contacts for opening all of said other route circuits which correspond to conflicting routes; a miniature track diagram of said track layout; control levers located on said track diagram adjacent the signal locations constituting the ends of said routes, each lever having normal and controlling positions; means for energizing any route circuit only upon the joint operation of the two control levers which belong respectively to the opposite ends of that route to controlling positions; and means for operating said track switches to normal and reverse positions as required for any route upon the energization of said route relay for that route.
- 85 13. In a switch and signal control system for railroad track layouts having power-operated switches and signals for governing train movement over various desired routes through said track layout, a miniature track diagram of the railroad track layout, control devices located on said track diagram adjacent the signal locations represented thereby and adapted to be manually actuated by an operator to close normally open entrance or exit contacts to define the corresponding signal location as the entrance or the exit end of a desired route, said exit contacts of said control devices being automatically restored to their open condition after the corresponding control device is manually released, said entrance contacts of said control devices remaining closed until the corresponding control device is manually restored to its normal condition, route establishing means including a plurality of route circuits each individually belonging to a corresponding route, each route circuit being energized by the joint actuation of the two control devices alone for the signal locations at the 90

ends of the corresponding route when these devices are actuated to close respectively their entrance and exit contacts, means for maintaining each route circuit energized after energization 5 thereof independently of the opened condition of the exit contact in that route circuit, and means responsive to the energization of a given route circuit for controlling the operation of all of the track switches in that route to the normal and 10 reverse position as required and for governing the clearing of a signal for the signal location having its associated control device actuated to close its entrance contact.

14. In a system for controlling the operation 15 of power operated switches and signals for a railroad track layout, said switches being operable to normal or reverse positions to provide a plurality of routes each providing for train movement from a signal at the entrance end of that 20 route to another signal at the exit end of that route governing train movement in the same direction, a control panel having thereon a miniature track diagram of said track layout, a plurality of manually operable control buttons located on said control panel adjacent the signal locations represented on said track diagram, an organization of route establishing circuits each 25 individually appertaining to a particular route between signal locations, contact means closed 30 in response to the manual actuation of a button adjacent a given signal location constituting the entrance end of a plurality of routes originating at said signal location for closing a normally open break in the various route establishing circuits for such routes, other contact means closed in 35 response to the manual actuation of a button for a given signal constituting the exit end of the plurality of routes terminating at such signal location for closing a normally open break in the various route establishing circuits for such routes, the route establishing circuit for a certain desired route being thereby closed and energized by the joint actuation of the two buttons alone which are associated with the signal locations 40 constituting the entrance and exit ends of that route, and relay means responsive to the energization of a route establishing circuit for concurrently governing the operation of the track switches in the corresponding route and also controlling the clearing of the signal at the entrance 45 end of such route, whereby the operator may establish any route desired by actuation of only two buttons belonging to the entrance and exit ends of that route.

15. In a system for controlling traffic on railroads, a track layout having a plurality of track switches and signals to set up different routes between signal locations and to control the passage of traffic thereover, a control panel having 50 thereon a miniature track diagram of said track layout, a manually controlled stay-where-put contact and a manually controlled self-restoring contact on said control panel adjacent each signal location on said track diagram, a route establishing circuit network having a plurality of route 55 circuits each individually appertaining to a particular one of said routes, each route circuit being energized by the closure of the stay-where-put contact for one end of its route and the closure of a self-restoring contact at the other end of its route, whereby the energization of a route 60 circuit requires manipulation of only two manually controlled contacts, relay means responsive to the energization of a given route circuit for governing the operation of the track switches in 65

the corresponding route and also clearing a signal at the end of such route corresponding to the stay-where-put contact operated, and stick circuit means for maintaining energized said relay means, as energized by said given route circuit, 5 dependent upon the operated condition of the stay-where-put entrance contact operated for the entrance end of such given route independently of the restoration of the self-restoring contact operated for the exit end of such given route. 10

16. In a system for controlling the operation of power operated switches and signals for a railroad track layout, said switches being operable to normal or reverse positions to provide a plurality of routes each providing for train movement from a signal at the entrance end of that route to another signal at the exit end of that route governing train movement in the same direction, a control panel having thereon a miniature track diagram of the track layout, a plurality of manually operable control buttons on a control panel adjacent the signal locations represented on the track diagram, contact means associated with each button and closed by its actuation, an organization of route establishing 20 circuits each individually appertaining to a particular one of said routes and each including the contacts controlled by the entrance and exit buttons associated with the ends of the corresponding route and being energized by the joint actuation of said entrance and exit buttons alone, and relay means responsive to the energization of a given route establishing circuit for concurrently governing the operation of the track switches in the corresponding route to the normal or reverse position as required and also clearing the signal at the entrance end of such route, whereby the operator may establish any route desired by actuation of only two buttons belonging to the entrance and exit ends of that route. 30

17. In a system for controlling switches and signals of a track layout having two parallel tracks between signals at opposite ends of such tracks and two crossovers arranged to allow the passage of traffic from any signal to either of the two signals at the opposite ends of said parallel tracks; a control panel having a miniature track diagram representing said tracks and switches; control buttons on said panel adjacent said represented tracks and at points corresponding to said signals; a circuit organization including route establishing circuits, one for each desired route between any two given signals at the opposite ends of said tracks, and each being energizable by the actuation of only the two control buttons on the panel for the signals at the opposite ends of the corresponding route, whereby the energization of a particular route establishing circuit requires the manipulation of only two manually operable control buttons; and relay 45 means responsive to the energization of a given route circuit for governing the operation of said crossovers to set up the corresponding route and also clearing a signal at the entrance to the route. 50

18. In an interlocking system for railroads, a track layout having track switches operable to provide two optional routes between two signal locations, a control panel having a miniature track diagram on which said switches are represented to correspond with the actual track layout, a manually operable control button for each of said two signals on said panel at positions on the diagram corresponding to the actual location of said signals, auxiliary manually operable control means, and route establishing means con- 65

trolled by the joint actuation of said two control buttons alone for operating said track switches to at times set up a particular one of said two optional routes, said route establishing means being controlled by the actuation of said auxiliary control means and said two control buttons for operating said track switches to at other times set up the other of said optional routes.

19. In a switch and signal control system for railroad track layouts having power-operated switches affording various routes for train movement between signal locations, said track layout providing at least two alternative routes between certain signal locations, a control panel having thereon a miniature track diagram of the track layout representing said switches and signal locations, a manually operable control button on said panel adjacent each of said signal locations at the entrance and exit ends of each of the various routes through the track layout, route establishing means manually governed exclusively by said buttons at the entrance and exit ends of the routes, said route establishing means acting in response to the joint actuation of the two control buttons alone for the signal locations at the ends of a given route to govern said switch and signal control means to operate the track switches to the normal or reverse position required to establish a predetermined route between such signal locations and to govern the clearing of a signal for governing train movement over said predetermined route.

20. In a switch and signal control system for a railroad track layout having power-operated track switches movable to different positions to provide different routes between signal locations, said track layout providing at least two alternative routes between the same entrance and exit signal locations, a control panel having thereon a miniature track diagram of said track layout, manually operable buttons located on said diagram adjacent the signal locations represented thereon, route establishing means responsive to the joint actuation of the two buttons alone for the signal locations at the entrance and exit end of any given route for operating the switches in that route to the normal or reverse position as required, said route establishing means acting in response to the operation of the buttons associated with the ends of said alternative routes to operate the track switches to set up a predetermined one of said alternative routes only, and separate manually operable switch levers one for each of the track switches involved in said alternative routes, said auxiliary switch control levers being effective to control the position of their respective switches independently of said route establishing means, whereby the operator may position the auxiliary switch levers in conjunction with the actuation of the buttons for the entrance and exit ends of the alternative routes and obtain a route different from the predetermined route that would be otherwise set up by the route establishing means upon operation of said buttons.

21. In a switch and signal control system for railroads, a track layout having a plurality of routes established by power-operated track switches operated to different positions such routes being for train movement between signal locations, a miniature track diagram of said track layout representing the switches and signals thereon, manually operable buttons on said track diagram adjacent the signal locations for designating such locations as the ends of dif-

ferent routes, a route establishing circuit organization having a route circuit for each desired route of said track layout, each of said route circuits being electrically isolated and energizable only by the joint operation of the two buttons for the opposite ends of its corresponding route, and electro-responsive means responsive to current flow in a given route circuit for operating the track switches in that route to positions to set up that route.

22. In a switch and signal control system for railroad track layouts having power-operated switches movable to different positions to establish routes for train movement between signal locations, a miniature track diagram of said track layout, buttons located on said track diagram adjacent the signal locations represented thereon and manually operable by an operator to define the entrance and exit end of a desired route, route establishing means governed by said buttons and constituting a plurality of circuit paths each independently appertaining to a particular route, the manual operation of a button for the entrance end of a desired route acting to apply an electrical potential to those circuit paths only which belong to predetermined routes originating at the corresponding signal location, the manual operation of a button for the exit end of such desired route acting to apply an electric potential of the other polarity to those circuit paths only belonging to predetermined routes terminating at the corresponding signal location, whereby only one circuit path for a predetermined route is energized by the buttons for the two signal locations at the ends of a route, and electro-responsive means responsive to the energization of any one of said circuit paths for governing the operation of track switches involved in the corresponding route to the normal or reverse position as required and for controlling the clearing of a signal at the entrance end of that route.

23. In a switch and signal control system for railroad track layouts having power-operated track switches and signals providing for train movement over various routes between signal locations, a control panel having thereon a miniature diagram of said track layout, said track diagram having representations of the signal locations portions of track and connecting switches; manually operable buttons located on said diagram adjacent the signal locations represented thereon, said buttons being manually operable by an operator to define the signal locations at the entrance and exit ends of a desired route, route establishing means for governing the position of the track switches and the indications of the signals, said route establishing means including a route circuit individually appertaining to each route and normally open at two end points only, and contact means responsive to the manual actuation of any button for a given signal location for closing the normally open break at the corresponding end of the route establishing circuits for the routes to or from that signal location, the manual actuation by the operator of the two buttons alone for the signal locations at the entrance and exit ends of any desired route acting to close only one route establishing circuit for a predetermined route between said signal locations.

24. A switch and signal control system for railroad track layouts having power-operated track switches and signals for train movement over various predetermined routes between signal

locations comprising, a miniature track diagram of said layout, manually operable devices located on said track diagram adjacent the signal locations represented thereon and operable manually by the operator to define the entrance and exit ends of a desired route, route establishing means for governing the operation of the track switches and the indications of the signals, said route establishing means comprising a plurality of route circuits each individually appertaining to a predetermined route between two signal locations, each route circuit being energized by the joint actuation of the two manually operable devices alone belonging to the signal locations for the opposite ends of that route, the manual operation by the operator of the devices for two given signal locations acting to apply operating potential to the route circuit for only one predetermined route between said signal locations and not to any other route circuit or a portion thereof, and relay means included in each route circuit and responsive to the energization thereof for governing the position of the track switches in that route and for preventing the energization of all of the route circuits for conflicting routes.

25. In a switch and signal control system for railroad track layouts having power-operated track switches movable to different positions to set up different routes for train movement between signal locations, a miniature diagram of said layout, a circuit controlling device located on said track diagram adjacent each of the points thereon corresponding with a signal location and manually operable by an operator to define the corresponding signal location at the end of a desired route, route establishing means including a plurality of route circuits one for each of the predetermined routes provided by said track layout for train movement between signal locations, each of said route circuits individually appertaining to a predetermined route and being energized individually by the manual operation of the circuit controlling devices for the corresponding signal locations, electro-responsive means in each of said route circuits responding to the energization thereof to govern the operation of the track switches involved in the corresponding route to either the normal or reverse position as required, said route establishing means acting in response to a manual actuation of the two circuit controlling devices alone for the signal locations at the ends of any given route to apply energizing potential to the electroresponsive means in the corresponding route circuit only, whereby the operator may set up a predetermined route between any two signal locations by merely operating the circuit controlling devices belonging to those signal locations.

26. In a switch and signal control system for railroads, a track layout having power-operated track switches to set up different routes between signal locations, a miniature track diagram corresponding to said track layout, a circuit controlling device located on said track diagram at each point corresponding to a signal location and manually operable by an operator to define its signal location as the entrance or exit end of a desired route, an organization of circuits governed by said devices for positioning the switches to set up the different routes, said circuit organization comprising a plurality of route circuits each individually belonging to a predetermined route, electro-responsive means included in said route circuits, said electro-responsive means included in a given route circuit responding to its

energization to govern the operation of the switches involved in that route to the normal or reverse position required, said circuit organization being such that the operation of any manually operable device designating that signal location as an exit point following the operation of any other manually operable device designating its signal location as an entrance point is not effective to complete any circuit for energizing any electro-responsive means unless there is a possible route for train movement between the signal locations for such manually operable devices.

27. In a switch and signal control system for railroad track layouts having power-operated track switches operable to different positions to provide various routes through said track layout between signal locations, said track layout including a plurality of signals governing train movement in the same direction on two or more tracks connected by track switches or crossovers, a control panel having thereon a miniature track diagram of said track layout, a manually operable device mounted on said control panel adjacent each signal location represented on said track diagram and adapted to be actuated by an operator to define the ends of desired routes for train movement through said track layout, and an organization of route establishing circuits responsive to the joint actuation of the two buttons alone for any two given signal locations at the ends of a desired route for governing the operation of the track switches in that route to the normal or reverse position as required, the electrical connections of said route establishing means providing no paths for the flow of current if two of the buttons for said signals governing train movement on the adjacent tracks are manually actuated at any time.

28. An entrance-exit switch and signal control system for governing the position of power-operated track switches and the indications of signals of a railroad track layout to establish various routes through said layout comprising, a control panel having thereon a miniature track diagram of the railroad track layout, switch control means for each switch operable to a normal or reverse condition to govern the operation of the corresponding switch to the normal or reverse position, a switch position relay for each switch governed in accordance with the position and locked condition of that switch, control buttons on said diagram adjacent each signal location and adapted to be manually actuated by an operator to define the corresponding signal locations as constituting the ends of a desired route, route establishing means governed by said control buttons and responding to the operation of the two buttons alone for the signal locations at the ends of any given desired route for governing said switch control means of the track switches in that route to the normal or reverse position as required to set up that route, a separate auxiliary switch control lever on said control panel for each switch and operable manually to govern the condition of the corresponding switch control means independently of said route establishing means, and an indicating lamp on said control panel for each switch governed by the corresponding switch control means and switch position relay, said indicating lamp for each switch being lighted whenever the position of the corresponding switch as manifested by its switch position relay is not in correspondence.

with the condition of the corresponding switch control means.

29. In a switch and signal control system of the type described for governing the position of power-operated track switches and the indications of signals to govern train movement through various predetermined routes of said track layout, a control panel having thereon a miniature track diagram of said track layout representing the signal locations and portions of track with the connecting switches, manually operable buttons on said track diagram associated with said signal locations and adapted to be actuated by an operator to define the ends of a desired route through said track layout, route establishing means responsive to the actuation of the two buttons alone for the ends of any given route for governing the operation of the track switches in that route to the normal or reverse position as required, a miniature switch point on said track diagram for each pair of switch points and movable to indicate visually by its relation to the representation on said diagram of adjoining portions of track the normal or reverse position of said switch points, means governed by said route establishing means for automatically operating said miniature switch points to positions corresponding with the route conditioned by the operation of said route establishing means, an indicating lamp on said track diagram adjacent each pair of switch points, and means governed by said route establishing means for lighting said indicating lamp for each of the track switches included in a route conditioned by said route establishing means.
30. A switch and signal control system for controlling the position of power-operated track switches and the indications of signals of a railroad track layout comprising, a control panel having thereon a miniature track diagram of the track layout, a manually operable device located on said track diagram adjacent each signal location represented thereon and adapted to be actuated by an operator to close an entrance contact or an exit contact to define the corresponding signal location as the entrance or the exit end of a desired route through said layout, route establishing means governed by the manual actuation of said devices and including a plurality of route circuits each belonging individually to a predetermined route, each of said route circuits being energized by operation of the two devices alone for the signal locations at the ends of the corresponding route only if these devices are operated to close respectively an entrance contact and an exit contact, a control circuit for each signal acting if energized to cause that signal to indicate proceed dependent upon the position of the track switches, and electro-responsive means included in said route circuits and responding to the energization of a given route circuit to control the operation of the track switches in the corresponding route to the normal or reverse position as required and for also closing said signal control circuits for one signal or the other at the ends of that route dependent upon which of the corresponding manually operable devices has been actuated by the operator to close its entrance contact.
31. In an entrance-exit type of switch and signal control system for railroad track layouts, a control panel having thereon a miniature track diagram of a track layout, said diagram having represented thereon the signal locations and the portions of track with their connecting switches,

a switch machine for operating each switch to the normal or reverse position, locking means for each switch acting if deenergized to prevent a change in the position of that switch, manually operable buttons on said diagram adjacent the signal locations and adapted to be actuated by an operator to define the corresponding signal location as the entrance or the exit end of a desired route, route establishing means responsive to the joint actuation of the two buttons alone for the ends of any given route for governing the operation of the switch machines of all of the track switches involved in that route to the normal or reverse position as required, switch position indicating means on said track diagram associated with each switch and governed by said route establishing means to indicate visually the controlled position of each switch, and a lock lamp on said track diagram adjacent each switch and automatically controlled by the corresponding switch locking means for indicating visually if the corresponding track switch is locked.

32. In a switch and signal control system of the entrance-exit type described for positioning track switches and controlling the clearing of signals for a railroad track layout, a miniature track diagram of the railroad track layout, circuit controlling devices located on said diagram adjacent the signal locations represented thereon and manually operable by an operator to define the entrance and exit ends of a desired route, a plurality of route circuits one belonging individually to each route for governing the operation of the track switches in that route to the normal or reverse position as required, each route circuit being energized by the joint manual actuation of the two devices alone for the signal locations at the ends of that route, and indicating means on said track diagram associated with each of the track switches and responding to the energization of said route circuits independently of the existing positions of the track switches for visually indicating on said diagram the position of the switches in any proposed route determined by the energization of the corresponding route circuit.

33. In a switch and signal control system for governing the position of power-operated track switches and indications of signals in a railroad track layout to provide various desired routes for train movement through said layout comprising, a miniature track diagram of said track layout, a manually operable device on said track diagram adjacent such signal location represented thereon and adapted to be actuated by an operator to close an entrance contact or an exit contact to define the corresponding signal location as the entrance or the exit end of a desired route, switch control circuits for each switch for governing the operation thereof to the normal or reverse position, switch position relays conditioned in accordance with the position and locked condition of said switches, a plurality of route circuits each one individually belonging to a particular one of the routes through said track layout, each route circuit being energized by the operation of the two devices alone for the signal locations at the ends of the corresponding route only if these devices are operated to close respectively an entrance contact and an exit contact, electro-responsive means included in said route circuits and responding to the energization of any given route circuit to control the energization of the switch control circuits of the

switches in the corresponding route to position those switches for that route and for also concurrently closing a break in the clearing circuit for one signal or the other at the ends of that route dependent upon which of the corresponding devices has been actuated to close its entrance contact, and means for each route governed by the corresponding route circuit for preventing closure of the signal clearing circuits for either signal for that route until the switch position relays of the switches in that route have all assumed conditions corresponding with the condition of the corresponding switch control circuits.

34. In an entrance-exit type of switch and signal control system for railroad track layouts, a control panel having thereon a miniature track diagram of the track layout, control buttons on said diagram adjacent the signal locations represented thereon and manually operable by an operator to define the corresponding signal location as the entrance or exit end of a desired route, switch control means for each switch for governing the operation thereof to the normal or reverse position, route establishing means governed by said control buttons and including a plurality of route circuits one individually belonging to a particular one of the routes through the track layout, each route circuit being energized by the joint actuation of the two buttons alone for the signal locations at the ends of that route, electro-responsive means included in said route circuits and responding to energization of a given route circuit to govern the switch control means of the switches involved in that route, miniature switch points on said track diagram movable to indicate visually the normal or reverse position of the several track switches, and means governed by said electro-responsive means and responding to the energization of any given route circuit for automatically operating said miniature switch points of the switches involved in that route to the normal or reverse position to indicate visually on said track diagram the position of these switches.

35. In a switch and signal control system of the type described for railroad track layouts having power-operated track switches, a control panel having thereon a miniature track diagram of the track layout, said track diagram representing the signal locations and portions of track with their connecting switches, manually operable buttons located on said control panel adjacent the signal locations represented on said track diagram and adapted to be actuated by an operator to define the signal locations at the ends of a desired route, route establishing means including a plurality of route circuits each belonging individually to a particular desired route, each of said route circuits being energized by the joint actuation of the two buttons alone belonging to the signal locations at the ends of the corresponding route, means responsive to the energization of any given route circuit for governing the operation of the track switches involved in the corresponding route to the normal or reverse position as required for that route, indicating means on said diagram adjacent each switch and operated automatically by the energization of a route circuit for a route including that switch independently of the existing position of that switch, said indicating means visually indicating on said track diagram adjacent each switch the position required of that switch for a route intended to be obtained by the energization of a route circuit,

and other indicating means on said control panel belonging individually to each switch and automatically governed in accordance with the operated position of that switch for visually indicating when that switch has operated to the position required by the energization of a route circuit.

36. In an entrance-exit type of switch and signal control system for track layouts having power-operated track switches, a control panel having thereon a miniature track diagram of said layout representing the signal locations and portions of track with their connecting switches, manually operable buttons on said diagram adjacent said signal locations, a plurality of route establishing circuits each belonging individually to a desired route through said track layout, each route establishing circuit being energized by the joint operation of the two buttons alone for the signal locations at the ends of that route, means responsive to the energization of any given route circuit for governing the operation of the track switches involved in that route to the normal or reverse position required for that route, and indicating means on said track diagram associated with each pair of switch points and responsive to the energization of said route circuits independently of the existing position of the corresponding track switch for visually indicating on said track diagram adjacent each switch the position required of that switch for the route intended to be obtained by the manual actuation of said buttons, defector track circuits for said switches, and other indicating lamps on said track diagram governed by said defector track circuits and maintained lighted independently of the condition of said route establishing circuits.

37. In a switch and signal control system for railroad track layouts having power-operated track switches, a control panel having thereon a miniature track diagram of the track layout, control buttons on said panel adjacent the signal locations represented on said track diagram and manually operable by an operator to define the corresponding signal locations as the ends of a desired route, route establishing means responsive to the joint operation of the two buttons alone belonging to the signal locations at the end of any given desired route for governing the operation of the track switches in that route to the normal or reverse position as required, locking means for each switch acting if deenergized to prevent operation thereof, circuit means for preventing energization of said locking means for the switches in an established route while a train is traveling through said route, and means governed by said locking means for rendering manual actuation of said buttons ineffective while said locking means for any switch is deenergized to create a stored controlling condition for that switch which would otherwise cause a subsequent operation of that switch when its locking means becomes energized, whereby an operator cannot pre-condition any of the switches involved in an established route for operation to a different position for any conflicting route and may not actuate the buttons for a conflicting route until the established route is unoccupied.

38. In a switch and signal control system of the entrance-exit type for positioning the power operated track switches and controlling the indication of signals to govern train movement through various desired routes of a railroad track layout, a miniature track diagram of said track layout, control buttons located on said track diagram adjacent the signal locations represented thereon,

and adapted to be manually actuated by an operator to define the signal locations constituting the ends of a desired route, separate route circuits belonging individually to said routes and 5 energized by the joint actuation of the two buttons alone for the signal locations at the ends of the corresponding route, each route circuit being normally effective when energized to govern the position of the associated track switches in- 10 volved in the corresponding route, means responsive to the presence of a train in the various portions of track involved in said routes, and means governed by said train responsive means for rendering each of said route circuits effective 15 to govern operation of the associated track switches only if the corresponding buttons are actuated while the portions of track in the corresponding route are not occupied.

39. In a switch and signal control system for 20 railway track layouts having power-operated track switches and signals for governing train movement over the various desired routes through said track layout, a control panel having thereon a miniature track diagram of said track 25 layout, control buttons located on said control panel adjacent the signal locations represented on said track diagram and manually operable by an operator to define the corresponding signal locations as the ends of the desired route, a plurality 30 of route establishing circuits each belonging individually to a particular one of the desired routes, each route establishing circuit being energized by the joint operation of the two buttons alone belonging to the signal locations at 35 the ends of the corresponding route and acting when energized to govern the position of the track switches to set up that route and control the clearing of a signal for that route, and means responsive to the presence of a train in any established route for permitting a route circuit for a 40 conflicting route to be effective to govern its track switches only if the buttons for energizing that conflicting route circuit are actuated by the operator after said established route has become 45 unoccupied.

40. In a switch and signal control system of the character described for governing the position of power-operated track switches and the indications of signals of a railroad track layout, 50 a miniature track diagram of said track layout, control buttons located on said diagram adjacent the signal locations represented thereon and adapted to be manually actuated by an operator to define the signal locations for the ends of a 55 desired route, a plurality of route establishing circuits each belonging individually to a particular one of the desired routes, each of said route circuits being energized by the joint actuation of the two buttons alone for the signal locations 60 at the ends of the corresponding route, electro- responsive means included in said route circuits for governing the operation of the corresponding track switches and controlling the indications of the corresponding signals, a lock relay 65 associated with each switch and acting when de- energized to prevent operation thereof, means governed by said route circuits for causing de- energization of said lock relays for the switches in the corresponding route, a signal clearing cir- 70 cuit for each signal closed only if the lock relays for the switches in the route for that signal are all deenergized, track circuit controlled means for preventing energization of said lock relays while a portion of track adjacent the correspond- 75 ing switch is occupied by a train, and means gov-

erned by said lock relays of the several switches and effective while a train is travelling through an established route for preventing any control of the switches in that established route by the manual manipulation of the buttons for any conflicting route unless said buttons are manually actuated at a time subsequent to the energization of the corresponding lock relays, whereby an operator cannot precondition any of the switches in an occupied established route for operation to 10 different positions while that route is occupied but must wait until the route becomes unoccupied before actuating the buttons for any conflicting route. 5

41. In a switch and signal control system for 15 railroad track layouts having power-operated track switches movable to different positions to establish various desired routes through said track layout, a miniature track diagram of said track layout representing the portions of track 20 and connecting switches in said track layout and the signal locations, manually operable control buttons on said track diagram adjacent the signal locations, route establishing means responsive to the joint actuation of the two control buttons alone for the signal locations at the ends of any desired route for concurrently governing the position of the track switches in that route, train responsive means associated with each switch and maintained deenergized by the presence of a train in a corresponding portion of track, and means governed by said train responsive means for preventing any control being imposed upon any of the switches in a train occupied established route by the manual actuation 30 of the buttons for any conflicting route unless such manual actuation occurs subsequent to the unoccupied condition of said established route, whereby an operator cannot precondition any of the switches in an established route to operate 40 to a different position while that route is occupied but must wait until that route is unoccupied before actuating the buttons for a conflicting route. 35

42. In a switch and signal control system for 45 governing the position of power-operated track switches and the indications of signals of a railroad track layout, a control panel having a miniature track diagram thereon corresponding to said track layout, manually operable control 50 means on said control panel adjacent each of the signal locations represented on said track diagram, route establishing means responsive to the joint operation of two manually operable control means for the signal locations at the ends 55 of a desired route for governing the operation of the track switches in that route, locking means for each switch adapted when rendered effective to restrain operation of that switch, a signal clearing circuit for each signal closed at one point 60 by the operation of said route establishing means to establish a route for said signal, each of said signal clearing circuits for a given route being closed only if the track switches in that route are operated to the proper positions and the locking 65 means of these switches is effective, and means responsive to the operation of said route establishing means to set up a given route for rendering effective the locking means of the switches involved in that route, whereby a signal cannot 70 clear for train movement over any given route until the switches in that route have operated to the proper position and the locking means for these switches is effective to prevent operation 75 of these switches to a different position. 75

43. In a switch and signal control system for railroads, a track layout including power operated track switches and signals for governing traffic thereover, a control panel having a miniature track diagram thereon corresponding to said track layout, manually operable control means on said control panel adjacent each of the signal locations represented on the track diagram, route establishing means responsive to the joint operation of two manually operable control means for the signal locations at the ends of a desired route for controlling the operation of the track switches in that route, locking means associated with each track switch and acting when effective to prevent further control of that track switch to a different position, each said locking means being controlled by said route establishing means, and a signal clearing circuit for a given signal controlled by said route establishing means to clear that signal only if the track switches for the route governed by such signal are in positions corresponding to their control by said route establishing means and only if the locking means for such switches have been rendered effective.

44. In a switch and signal control system for railroads, a railroad track layout including two adjoining interlocked groups each comprising a stretch of track having track switches and signals at the ends of said stretch for governing train movement in both directions, manually operable buttons associated with the entrance and exit ends of said interlocked groups, means associated with each interlocked group and responsive to joint actuation of the buttons only at

the entrance and exit ends of that group for automatically establishing a route over the corresponding stretch of track by operation of the switches to positions required and clearing a signal at such entrance end for train movement into the stretch, and means for preventing the clearing of signals at the same time for train movement in opposite directions in said stretches of track.

45. In a switch and signal control system for railroads, a railroad track layout including two adjoining interlocked groups each comprising a stretch of track having track switches and signals at the ends of said stretch for governing train movement in both directions, manually operable buttons associated with the entrance and exit ends of said interlocked groups, means associated with each interlocked group and responsive to joint actuation of the buttons only at the entrance and exit ends of that group for automatically establishing a route over the corresponding stretch of track by operation of the switches to positions required and clearing a signal at such entrance end for train movement into the stretch, said means including clearing circuits for the signals at the extreme ends of said interlocked groups, and means for preventing energization of either of said signal clearing circuits if a route is established in the other interlocked group for an opposing train movement but permitting such energization if the route established is for train movement in the same direction.

SEDGWICK N. WIGHT. 35

DISCLAIMER

2,121,846.—*Sedgwick N. Wight, Rochester, N. Y.* INTERLOCKING SYSTEM FOR
RAILROADS. Patent dated June 28, 1938. Disclaimer filed December 12,
1940, by the assignee, *General Railway Signal Company*.

Hereby enters this disclaimer as to claim 18 of said Letters Patent.
